Frederick E. Smith, Southampton, Pa., assignor to the United States of America as represented by the Secretary of the Navy

Filed Feb. 20, 1958, Ser. No. 716,518

29 Claims. (Cl. 343—7)

(Granted under Title 35, U.S. Code (1952), sec. 266)

The invention described herein may be manufactured and used by or for the Government of the United States of America for governmental purposes without the payment of any royalties thereon or therefor.

The present invention relates to an intercept computer and more particularly to an intercept computer in which the plan position data of an early warning radar is used for computing the heading and time required for an interceptor aircraft to intercept a moving target at a remote unique point in space.

Various methods have been devised for computing a collision course approach and the flight time required for an interceptor aircraft to successfully intercept a moving target at a remote point in space. The problem is capable of solution by means of analog computers which have been previously programmed. Hand calculators using the display data of a plan position indicator (PPI) in an early warning radar have also been employed. However, the devices of the prior art generally possess various inherent limitations which preclude a feasible solution of the problem, especially in view of the supersonic speeds of contemporary aircraft. Further, because of space and weight considerations, analog computers, in general, do not conveniently adapt for airborne use, in addition to the fact that they are susceptible to operational difficulties peculiar to these instrumentalities. Hand calculators lack accuracy and fail to have a facility commensurate with the tactical requirements.

The intercept computer of the instant invention utilizes the video data presented on the screen of a PPI scope in an early warning radar and augments the presentation to include an electronically generated slewable cursor and circle which are displayed in time shared relationship with the normal radar sweeps so that the radar scope operator is enabled to readily compute both a collision course approach to an enemy aircraft and the time required to make the interception from the position of a friendly aircraft. The aforesaid cursor and circle are each associated with the target and interceptor video, respectively, under selective control of the operator such that an intersection therebetween yields the desired solution in accordance with the simple equation

$$\text{Distance} = \text{Speed} \times \text{Time}$$

With the aid of a selectively controllable cursor strobe or dot superposed on the cursor sweep which itself is rotatably controlled about its origin, a determination of the target course and speed is initially made from a knowledge of the immediate history of the target video, which remains momentarily visible due to screen persistence. Corterminous with this determination, the circle of radius proportional to the instantaneous product of time and a predetermined interceptor speed is superposed onto the interceptor's position as viewed on the screen. Under control of the radar scope operator, a timing mechanism provides for extrapolating current target position into future time position by varying the time parameter, simultaneous with an increasing interceptor circle radius until an intersection occurs therebetween at a unique intercept point. A circle azimuth dot movable about the periphery of the circle facilitates the determination of an intercept heading. A "Time-to-Intercept" indicator is automatically set during this operation and continually indi-

2

cates the flight time remaining for the interceptor travelling a predetermined rate of speed to intercept the target. This information is continually available during the course of an intercept problem and is relayed to the friendly interceptor aircraft by a conventional data link transmission means. Thus, a combat information center (CIC) incorporating the instant invention is capable of directing the intercept of enemy aircraft with dispatch. The instant invention has been successfully employed with a mobile CIC in conjunction with an airborne early warning radar. The presentation under such operational circumstances is both north and ground stabilized so that the conveying aircraft may be in motion, and yet stationary targets will remain in a fixed position on the face of the cathode ray tube (CRT), as is understood.

An object of the present invention is to locate the point in space where the flight paths of two aircraft may be made to intersect by having control over the flight of one of the aircraft.

Another object is to provide an intercept computer in which the heading and the flight time required to intercept a target from the position in space of an interceptor aircraft may be readily determined in a finite time interval consonant with tactical requirements.

Still another object is to provide an intercept computer in which the heading and the time required to intercept a target at a remote point in space from the position of an interceptor aircraft is uniquely determined by the point at which a target strobe superposed on a slewable cursor sweep mutually intersects a circle of radius proportional to the instantaneous product of time and a predetermined interceptor speed.

A still further object of the present invention is the provision of an intercept computer in which a collision course approach and the time required to intercept a moving target from the position of an interceptor aircraft is computed in accordance with the equation

$$\text{Distance} = \text{Speed} \times \text{Time}$$

such that the respective distances traversed in equal intervals of future time by the interceptor aircraft and the target is predicated upon the known speed of the friendly interceptor aircraft and the speed of the target determined by the coincident travel of target video with an electronically generated strobe superposed on a cursor sweep angularly disposed to coincide with the target heading.

A final object of the present invention is to provide in an intercept computer a timing mechanism for rendering a chronometric rate of rotation required in the multiplication process, wherein the current time established by the aforesaid chronometric rotation may be manually projected into future time to effect determination of a target intercept point.

The exact nature of this invention as well as other objects and advantages thereof will be readily apparent from consideration of the following specification relating to the annexed drawings in which:

FIG. 1 is a plan position view of the electronically generated cursor and circle representatively displayed in relative orientation on the screen of a PPI scope,

FIG. 2 is a simplified diagram of the speed and time multiplication system incorporated in the instant invention,

FIGS. 3a, 3b, and 3c is a composite functional block diagram of a preferred embodiment of the instant invention,

FIG. 4a through FIG. 4h is a composite detailed electrical schematic drawing of the invention,

FIG. 5 is a timing chart particularly showing the relative amplitude and timing relationships of the more perti-

net wave forms found at various points in the electrical circuits of the inventive intercept computer.

FIG. 6 is a diagrammatic view in isometric form of the timing mechanism of the instant invention.

FIG. 7 is a diagrammatic view of the portion of the timing mechanism more pertinently associated with the running mode of operation, and

FIG. 8 is a diagrammatic view of the portion of the timing mechanism more pertinently associated with the reset mode of operation.

Referring now to the drawings, wherein like reference characters designate like or corresponding parts throughout the several views, there is shown in FIG. 1 a representative PPI display of an early warning radar set which incorporates the inventive intercept computer. Cursor 11 and circle 12 are portrayed typically disposed wherein the size of the circle has been expanded during the advance time mode of operation of the timing mechanism to intersect the cursor at the intercept point P. This mode of operation will be subsequently described with greater particularity with relation to FIG. 6. Cursor 11 is illustrated in prolongation with successive plots of target video T, thus establishing coincidence of the cursor with the direction of flight of the target, the speed of which is determined by coincident travel of the target video T with an electronically generated cursor dot or strobe S movable along the cursor and shown superposed onto the intercept point P in the view of FIG. 1. The interceptor circle 12 is portrayed with its center at the friendly interceptor aircraft video I. Since its radius is directly proportional to the product of the interceptor speed and time, the mutual intersection of cursor sweep 11 and expanded circle 12 coincident with projected cursor dot S at point P yields the intercept heading α , measured from a north reference as indicated. To facilitate a measurement of this angle, a circle azimuth dot D is provided. Upon retracting to current time operation from advance time operation, a time-to-intercept indicator is automatically set, and thereafter indicates continuously the flight time remaining for the interceptor travelling a predetermined rate of speed to intercept the target.

FIG. 2 portrays a simplified showing of the speed and time multiplication system incorporated in the instant invention. The specific computation hereinbefore denoted involves only the multiplication of speed and time to produce distance. The basic technique for performing a solution of this equation is best delineated with respect to the simplified showing provided in this view. Accordingly, there is schematically illustrated in FIG. 2 a timing mechanism 90 comprising a motor 16 having constant speed characteristics serving in the instant invention a chronometric function, a differential 17 including a time modifier control 19, a time dial 18 utilized as a time-to-intercept indicator, and time potentiometers R13 and R14. The elements herein set forth are mechanically coupled, as indicated by the dotted lines, and will be discussed subsequently in greater particularity with respect to FIGS. 6, 7 and 8. The chronometric rotation of motor 16 will be seen in FIG. 2 to be transmitted through differential 17 and time dial 18, to the time potentiometer housings or resistive portions proper of R13 and R14, which thereby rotate at a constant rate of speed relative to the respective wipers. Time modifier control 19 is a manual input to differential unit 17 operable to modify the relative positions of the potentiometer wipers with respect to the respective housings or resistive portions of the potentiometers. The setting of target speed control potentiometer R80, a function of target speed as determined by progression of target video on the face of the PPI scope is inserted by manual adjustments as necessary to maintain cursor dot S coincident with the target T as it advances along the cursor. Similarly, the setting of the interceptor speed control potentiometer R90 is manually adjusted to the known speed capability of the interceptor aircraft.

Apropos of the structure depicted in FIG. 2, and understanding of the multiplication process performed in the inventive intercept computer may be had by a consideration of time potentiometer R14 with target speed control potentiometer R80. Assuming a constant D.C. voltage X to be impressed across potentiometer R14, the wiper thereon linearly fractionates this voltage in direct proportion to the elapsed time by virtue of the constant speed drive transmitted from chronometric motor 16. Since coefficient K₁ has a range between 0 and 1, the potential between the wiper and ground is K₁X, an analog voltage which thus relates to the elapsed time in the computer. With the aid of time modifier control 19, time may be projected into the future, and accordingly, any future time interval may be expressed as a proportionate voltage. The voltage K₁X will be observed to be the reference voltage for target speed control potentiometer R80. Consequently, K₁X is further modified by a second coefficient K₂, which has a similar range and is set according to the target speed. Hence, the analog voltage K₁K₂X available at the potentiometer 21 relates to target distance, already traversed or anticipated during a selected time interval. This voltage is then applied to the circuits of the cursor dot generator.

Inasmuch as the function and operation of potentiometers R13 and R90 are similar to that of potentiometers R14 and R80 with regard to the multiplication process, the explanation set forth above is deemed sufficient. A minor but significant variation exists in that the reference voltage Y is sinusoidal in this instance to facilitate the electronic generation of a circular pattern. The magnitude of analog voltage C₁C₂Y relates to interceptor distance, traversed or anticipated in the same selected time interval. This voltage is thence supplied to appropriate circuits for the generation of the interceptor circle.

Referring next to FIG. 3a, FIG. 3b, and FIG. 3c, there is shown in a consecutive arrangement of these views, a functional block diagram of a preferred embodiment of the instant invention. As hereinbefore mentioned, the electronically generated cursor and circle are presented in time shared relation with the radar PPI sweeps. The early warning radar set which incorporates the instant invention has a pulse repetition rate (PRF) of 300 per second or thereabouts, and in accordance with this design criterion, the instant invention provides for every tenth sweep to be alternatively displayed on the PPI screen either as a cursor sweep or as a circular pattern. Therefore, the recurrence rate at which either the cursor or circle is presented occurs at a 15 c.p.s. rate, which is compatible for comfortable viewing without evidence of flicker. The sweep generating means including numerous components represented by various blocks in FIGS. 3b and 3c is arranged to accomplish this objective in the manner described below. A transmitter pulse amplifier 24 is depicted in FIG. 3b, the twofold purpose of which is to amplify a positive radar trigger appearing at input terminal 23 and invert the phase of the signal in order that it may be of a desired negative polarity required in subsequent applications thereof. Transmitter pulse cathode follower 25 functions to provide isolation in addition to supplying a low impedance trigger of approximately 80 volts to the multivibrator gate 26 and phantastron cathode follower 77. The sweep limiter and charging clamp 27 is interrelated in its actions with multivibrator gate 26 to concurrently produce a pair of bistable output voltages of a substantially square wave character and the requisite sawtooth waveforms necessary for effecting sweep lengths corresponding to 20, 50, 100 and 200 mile ranges. The square wave voltages of approximately 80 volts in amplitude are opposite phase and occur in response to the triggers appearing at terminal 23. The respective character of these voltage waveforms in relative amplitude and phase relation may be observed in the timing chart of FIG. 5, waveforms B and D being typical outputs of multivibrator gate 26 for a selected range sweep length.

The sawtooth amplifier 28 amplifies the sawtooth voltage which is thus applied to a synchro driver 29. The latter stage is a power cathode follower which feed into the rotor windings of synchro resolvers 31 and 32, the respective stator windings of which are disposed ninety electrical degrees apart. The purpose of these resolvers is to convert the applied sawtooth voltage into N-S and E-W sawtooth components, which are proportional to the angular displacement of the respective rotors. The rotor of resolver 31 is indicated by the dotted line notation to be mechanically coupled with the servo follow-up drive of the antenna system, and its rotation is thereby in synchronism with the radar antenna. The rotor of resolver 32 is angularly displaced under manual control of the operator by means of cursor bearing control 33. The sawtooth components from both resolvers are applied to the PPI and cursor switch stages 34, 35, 36 and 37, comprising dual triode type envelopes which are responsive to appropriate gating pulses, permitting selective application of the PPI and cursor sawtooth voltage components to the N-S and E-W push-pull deflection amplifiers 38 and 39, in accordance with the successive presentation of nine PPI sweeps for each circle or cursor sweep. With respect to either the circle or cursor presentation, N-S and E-W components of clamping voltage maintained at the level of the slewing input signal are supplied to amplifiers 38 and 39. Provision is made to clamp the normal PPI sweeps at ground potential, preventing the location of the start of the trace from shifting due to rotation of the sweep. It will be observed in this respect that the sweep signal outputs of the switch stages are in common connection with the respective outputs of the PPI and cursor gated clamp stages 41, 42, 43 and 44. Thus, in general it may be presently noted that a composite sweep signal which includes a D.C. slewing component is supplied to the push-pull deflection amplifiers, the output load of which contains an inductive yoke L907 having deflection coils which are quadrantly disposed about the neck of the cathode ray tube 45. Coherent unblanking or lowering of the cutoff bias on the CRT is provided by a brilliance and blanking circuit 48. Hence, as summarily described above with respect to the composite functional block diagram of the instant invention, PPI and cursor sweeps are generated and selectively displayed coincidently with intensity modulation of CRT45.

In addition to being of transcendent importance in the generation of sweep signals, the square wave output of multivibrator gate 26 is supplied to count-down multivibrator circuit 46. As previously denoted, this waveform has a recurrence rate which is equal to the PRF of the radar triggers. It is the purpose of multivibrator 46 to fractionate or count down this recurrence rate by ignoring a certain number of differentiated waveforms, precisely nine cycles, and responding to the tenth waveform. Multivibrator 46, therefore, functions to generate a substantially asymmetrical bistable voltage at a recurrence rate of 30 c.p.s. This voltage is supplied to switch gate generator 47 wherein two square waves of opposite polarity are produced having stable limits which vary between +110 and -240 volts. The cyclic period of these specific bistable voltages is unchanged, being of the same duration as the output from count-down multivibrator 46. To better delineate from a systems point of view the plurality of gating functions served by these particular square wave signals, they have been designated the PPI and cursor side outputs, which are representatively indicated in FIG. 5 by waveforms E and F, respectively.

The brilliance and blanking circuit 48 is of a design requiring both the PPI and cursor gating signals in addition to the bistable signal of multivibrator 26 to provide time shared intensity modulation of the cathode of CRT45, and of particular note, relay driver 50 in FIG. 3a is fed the signal associated with the PPI side. The latter stage effects actuation of a pair of differentially operated high speed relays K301 and K302, at a repeti-

tion rate which is one-half the incoming signal. Therefore, the respective contacts of these relays complementally switch back and forth at a 15 c.p.s. rate, that is to say, when the alphabetically designated contacts of K301 are in the down position shown, the lower alphabetically designated contacts of K302 are in the up position, and vice versa. Switch gate generator 47 also is a source of gating signal to the PPI and cursor switch stages 34, 35, 36 and 37, the PPI and cursor driver cathode followers 55 and 56, and video and strobe switches 52 and 53. The pertinence of these PPI and cursor gating signals will become more apparent in subsequent description of the system operation in relation to the timing chart depicted in FIG. 5.

With respect to the description set forth in connection with the representative PPI display shown in FIG. 1, the cursor strobe S and azimuth circle dot D including radar video are selectively inserted on a time shared basis into the video channel of the instant intercept computer. In FIG. 3c radar video is applied at terminal 49 and undergoes amplification in video amplifier 51 where it emerges as a positive signal voltage. A video switch 52 upon receipt of a PPI gating signal from switch gate generator 47 permits passage of the video to cathode follower 54 during generation of the radar PPI sweeps. Strobe switch 53 functions in a comparable manner to alternately insert into the video channel positive spike voltages representing the azimuth circle dot D and cursor dot S upon being conditioned by the gating signal from the cursor side. Hence, the positive waveform presented at cathode follower 54 consists of a composite signal voltage which includes azimuth circle and cursor dot voltages and radar video. The positive signal from cathode follower 54 is appropriately clamped by clumper 60 and applied to the grid of CRT45. Thus, in the manner herein described the video channel comprising the elements set forth above facilitates the generation of a coordinated time shared display.

The structural elements particularly portrayed in FIG. 3a provide in general for the consummation of the multiplication processes of the instant invention, the generation of sinusoidal components for presentation of a circular pattern, the development of the aforesaid cursor dot and azimuth circle dot, and the development of D.C. positioning voltages to permit selective slewing of the cursor and circle. In this regard, oscillator 57 fulfills a major role, being a stable source of sinusoidal voltage having a frequency of 1000 c.p.s. or thereabouts. The voltage of oscillator 57 is applied across circle time potentiometer R13 and cascode resolver driver 66. Timing motor and differential unit 15 is shown to be mechanically ganged with cursor and circle time potentiometers, R13 and R14, which rotate, each producing a voltage proportional to time. A time modifier hand control 19 is provided to augment the rotation of the potentiometers relative to their respective wipers. A time dial 18 is also mechanically connected as denoted and indicates the time remaining for interception, or as more familiarly termed the "time-to-go." The A.C. voltage of potentiometer R13 is applied to circle speed potentiometer and cathode follower 58, wherein a magnitude of A.C. signal voltage is resolved which is proportional to the product of the interceptor speed and time. Manual interceptor speed control 72 is set in accordance with the predetermined speed of the interceptor. The 90° phase shift network and push-pull amplifier 59 transforms the applied sinusoidal signal into two discrete voltages 90 electrical degrees apart to facilitate the generation of a circular pattern. These A.C. components thereupon undergo push-pull amplification and are supplied to an A.C. and D.C. component mixer 61, which functions to superimpose these components onto a D.C. positioning voltage developed in circle positioning circuit 63. A joystick control 62 is mechanically linked by means of a conventional gear arrangement to effect movement of a plurality of potentiometers which develop

positioning voltages having magnitudes and polarities which correspond to displacement of the joystick from its neutral position. Thus, at the lower contacts *a*—*b*—*c*—*d* of relay K301 are presented A.C. components in requisite phase relation for generation of a circular pattern, and which are each superimposed on a D.C. level, the magnitude and polarity of which are a function of the position of the joystick. In a comparable manner, the purpose of cursor positioning circuit 65 is to establish a quadrantal number of discrete D.C. voltage levels which correspond to the position of joystick 64, thereby providing control over the location of the cursor on the face of the CRT.

Cursor time potentiometer R14 is supplied a D.C. voltage, a fractionated amount thereof being continuously apportioned according to time. Cursor speed potentiometer and cathode follower 73 accepts the fractionated voltage and produces in the output circuit thereof a low impedance D.C. voltage of exceptionally linear characteristics that is proportional to distance. Cursor speed control 74 which modifies the relative position between wiper and the resistive portion of the potentiometer proper is manipulated under control of the operator to assure coincidence of the cursor dot S with the target video as displayed on the screen of the PPI scope. A D.C. amplifier 75 performs amplification of the voltage level in addition to providing a measure of isolation. A two position selector switch 76, illustrated in FIG. 3b, is arranged to accept the output of D.C. amplifier 75 in the computer position. In the alternate radar position, switch 76 affords a convenient input from the range delay circuits of the radar, and in this respect, its specific application will be more apparent in later discussion in connection with the detailed schematic drawings of the instant invention. Assuming switch 76 to be in the computer position, the phantastron cathode follower 77 and phantastron 78 combinatively provide a bistable voltage having a duration in one of its stable states which is directly proportional to the magnitude of the voltage level of D.C. amplifier 75. This bistable voltage waveform is applied to a delayed trigger amplifier 79, whose output is a positive differentiated spike voltage of approximately 35 volts, selectively delayed an amount proportional to the D.C. output level of amplifier 75. This spike waveform is applied to blocking oscillator 81, shown in FIG. 3c, which responds thereto and produces a low impedance strobe or cursor dot voltage which is made available at the lower paralleled *a*—*b* contacts of relay K302. Actuation of K302 positioning its armature in the down position permits the strobe voltage to be inserted into the video channel at strobe switch 53 in FIG. 3c upon appropriate gating. Thus, a strobe or cursor dot is provided in accordance with inventive concepts of the instant intercept computer.

In contrast to the specific use of essentially a D.C. signal for generating the cursor dot voltage, the structure for effecting an azimuth circle dot relies upon the sinusoidal voltage of oscillator 57. A cascode resolver driver 66, illustrated in FIG. 3a, obtains its signal excitation from this source as previously denoted. The purpose of resolver driver 66 in addition to providing isolation is to present an exceedingly low impedance 1000 cycle signal to circle azimuth control resolver 68. The latter element resolves the applied input signal into two right angle voltage components as a function of the angular displacement of manual intercept heading control 67, which is mechanically linked in common with intercept heading indicator 82 and a rotor winding, not illustrated in FIG. 3a. Phase shift mixer 69 comprising a resistive-capacitive network recombines the components in a manner to effect phase shift of the A.C. signal in direct proportion to the angular rotation of control 67. The resultant sinusoidal signal emerging from mixer 69 may have its phase retarded 0-360° with respect to the output of oscillator 57 and is thence applied to azimuth dot generator 71, which comprises a two stage clipper amplifier, an RC shaping net-

work, and a blocking oscillator. Collectively the elements making up azimuth dot generator 71 convert the phase shifted signal into a strobe voltage, which is made available at the upper paralleled *a*—*b* contacts of relay K302. The armature of this relay in its up position, as shown, provides continuity to the video channel for insertion of the strobe voltage at strobe switch 53. It is of course manifested on the screen of the PPI scope as the azimuth circle dot D, depicted in FIG. 1.

The slewing potentials which locate the start of either the cursor or circle trace on the PPI screen are shown in FIG. 3a and FIG. 3b to be selectively applied to the respective N-S and E-W inputs of slewing cathode followers 83, 84, 85 and 86 through the contacts of relay K301. The respective outputs of these stages are thence directly applied to PPI and cursor gated clamp stages 41, 42, 43 and 44, which upon receipt of appropriate gating signals permit the deflection amplifiers of the instant computer to be clamped at the level of the slewing potential. Provision is made for clamping the normal radar PPI sweeps at a zero level potential by grounding the respective inputs of stages 41 and 43, as indicated. Thus, the clamping means set forth assure that the various traces start from the same point of reference on the PPI screen. The gating signals for the PPI and cursor gated clamp stages are obtained from the PPI and cursor driver cathode followers 55 and 56. The latter stages are selectively fed in time shared relation by PPI and cursor gate amplifier 87, which has dual output gating pulses, one of which is directly coupled to cathode follower 55. The other output is supplied to cathode follower 56 through contact *c* of K302 when the armature is disposed downwardly, its normal disposition in cursor application. When disposed upwardly, the normal disposition for circular pattern presentation, contact *c* supplies a cutoff bias to stage 56. In a similar manner, contact *d* of K302 in the downward position is effective to lower the cutoff bias on cursor switch stages 36 and 37, rendering these tubes conductive during cursor application. The precise functional significance of the gating and conditioning potentials associated with switch contacts *c* and *d* of relay K302 will be better appreciated in subsequent reference to the timing charts of FIG. 5 in connection with discussion of the system operation.

Hence, the structure as denoted in the functional block diagram of the inventive intercept computer provides for a plurality of integrated functions to be performed. Electrical circuit provisions have been set forth for performing the multiplication process, consonant with the generation of a coordinated time shared presentation consisting of cursor and circle traces integrated with normal radar PPI sweeps. In addition, cursor and azimuth circle dot voltages are developed and superposed onto the cursor and circle, respectively, for application in accordance with inventive concepts. The composite display as viewed on the PPI screen is coherently intensified by appropriate brilliance and blanking circuits.

Referring now to the views of FIGS. 4a through 4h, there is illustrated in a composite showing of these views a detailed electrical diagram of the instant invention. It is to be noted that the alphabetical designations bordering these views are to be understood as points of common connection between the various sheets of the drawing, provided to facilitate relative orientation of the several sheets comprising FIG. 4.

Apropos of the matter of coordinating the views, it is deemed appropriate to consider first the sweep generating means of the instant invention with relation to the schematic showing thereof in FIG. 4g. While the sweep generating means illustrated therein is of a type existing in the indicator portion of the radar set incorporating the instant invention, it has been necessarily modified to facilitate time shared PPI display in accordance with inventive concepts. FIG. 4g, therefore, is a schematic illustration of a modified form of sweep generating means, and, it is to be further noted that the numerical underlined designa-

tions of the individual electrical circuits therein indicated correspond to those used to identify various components in the composite block diagram of FIGS. 3a, 3b and 3c. With respect to FIG. 4g, positive radar triggers having a minimum amplitude of about 2.5 volts and a PRF of 300 or thereabouts appear at terminal 23. Resistor R901 functions to terminate the coaxial cable which supplies these triggers. Transmitter pulse amplifier 24 employs a pentode V901, the grid circuit of which has a protective network consisting of R903 and C903 which function only when the input signal is too high in amplitude. The resistor R903 serves to limit the flow of grid current to a safe value, while the capacitor prevents integration of the signals which would otherwise occur, due to the high value of resistance used in the grid circuit, together with the stray wiring capacity. The plate voltage for this stage is supplied from a +275 volt bus through its plate load consisting of R905 and L901, the latter being a shunt peaking coil. This stage is otherwise conventional. The output signal taken from the plate circuit consists of negative pulses with an amplitude of the order of 75 volts, and is applied to the grids of both triode sections of V902 of the transmitter pulse cathode follower 25. This stage employs a type 2CS1 dual triode, which is exemplary of the type copiously employed in the instant invention. Resistors R2607 and R914 produce the bias for the respective halves of this tube and have been selected to develop approximately +125 volts at the cathodes of V902. This choice of biasing allows the negative pulses arriving in the grid to produce full voltage swing of the cathodes. The respective outputs of transmitter pulse cathode follower 25 are taken from the cathode and are of the same polarity and approximately the same amplitude as the incoming signal. With respect to facilitating the delineation of structure involving envelopes or tubes containing a double set of elements, a convention has been adopted wherein the respective left and right halves of a tube, or the upper and lower portions as the case may be, are alphabetically designated as A and B, which are thence affixially joined with the associated tube designation. Thus, the first half of V902 is designated as V902A.

Multivibrator gate 26 employs both triode sections of V907 in a free-running multivibrator circuit whose operating frequency is approximately 60 cycles. Its basic operation is conventional. This stage is capacitively coupled through C917, and upon application of a negative pulse from V902A, normal multivibrator action is initiated. A square wave voltage of about 80 volts in amplitude is respectively developed across R948 and R956, the duration of which in either of its bistable states is commensurate with the selected range sweep length. These voltages are opposite in phase and are representatively indicated in FIG. 5 by waveforms B and D, which are the outputs of V907A and V907B, respectively. It should be understood that with different range sweep lengths the waveforms produced in the output of multivibrator gate 26 have a correspondingly varied asymmetry. The manner in which such characteristic is effected is described in connection with the sweep limiter and charging clamp circuit 27.

In order to linearly deflect the electron beam of the cathode ray tube magnetically, the sweep limiter and charging clamp circuit 27 provides for the application of a trapezoidal waveform of current to the deflection coils. V910B, one section of a 2CS1 dual triode, is used as a sweep charging clamp to initiate the charging process. A positive square wave from the cathode of V907B is applied to the cathode of V910B, and cuts off the quiescent plate current through this triode section. When plate current is cut off, the plate voltage begins to rise exponentially across a charging network connected between the plate circuit of V910B and ground. This network consists of R972, C930, C931, C932, R973 and either R970 or R970 plus R971, depending upon the position of switch S923A, which is one section of a multisection four posi-

tion switch. Since the charging current of the capacitor network flows through R972, a voltage rise is produced across this resistor during the time that the capacitors are charging. As only a small portion of the charging curve of the capacitor network is used for the actual sweep signal, the current through resistor R972 may be considered essentially constant for the duration of the sweep signal. It is this voltage rise across R972 that produces the pedestal portion of the trapezoidal waveform. The square wave that is applied to the cathode of V910B is also applied across C925, C926 or C927, depending upon the position of S923c. The time constant of this network is very short in comparison to the time of the applied square wave with the result that the leading edge of the applied square wave is differentiated, and a pulse is produced across R972. This positive pulse is combined with the pedestal portion developed across R972, and appears as the spike on the leading edge of the trapezoidal waveform. The charging curve of the capacitor network, C930 and C931, would normally be exponential; however, the series resistor R973 and capacitor C932, connected across C930, alter the exponential rise in a manner which increases the linearity of the exponential rise, functioning in effect as a low-frequency compensating network. The plate of V910B is coupled to the grid of V910A through R969. The cathode of V910A has a positive voltage applied from the voltage divider consisting of R965, R967 and R966, the sweep length adjust 80 miles, or R968, the sweep length adjust 200 miles, depending upon the position of the S923b. This voltage is sufficient to bias V910A beyond cutoff. As the capacitor network charges, in the production of the sweep length waveform, the plate voltage of V910B rises until a point is reached at which the voltage coupled through R969 is no longer capable of maintaining cutoff of V910A. Plate current begins to flow, producing a voltage drop across R946. This drop is applied to the grid of the second triode section of V907B through C918. Since this triode section is conducting, the negative signal results in a decrease in plate current through this triode section. Due to the large amount of coupling between the two triode sections of V907 of the multivibrator gate 26, the conducting tube is rapidly driven beyond cutoff, and the cutoff section is brought into conduction. The multivibrator is thus in a condition to receive the next transmitter pulse. In resuming its original condition, the multivibrator gate 26 generates a negative square wave, which is applied to the cathode of V910B, and drives this tube into conduction. As soon as V910B begins to conduct, the capacitor sweep-generating network is discharged, and the sweep is ended. A sweep signal of positive polarity is thus developed across the charge network and taken from the junction of C932 and R973, and applied to the grid of V911A of sawtooth amplifier 28 through R974, a 1,000 ohm resistor which prevents grid current flow and suppresses parasitic oscillations. A representative sawtooth sweep voltage is portrayed in FIG. 5 by waveform C.

The dual triode V911 employed in sawtooth amplifier 28 is connected as a conventional cascaded amplifier. The output sweep signal voltage of a positive polarity is developed across R985 and is capacitively coupled through C937 to the synchro driver 29. Since the rate of trace movement across the screen of CRT45 depends upon the amplitude of the sweep signal, a higher amplitude signal is required to produce the 20 mile sweep than is required to produce the 50, 100 and 200 mile sweeps. Accordingly, in order that the gain of amplifier 28 may be reduced as a desired sweep length is increased, a negative feedback voltage is applied at this stage from the common cathode circuit of V30 and V31, which function as cathode followers connected in parallel to increase the power driving capabilities thereof. Fixed bias for this stage is applied through R994 from a voltage divider consisting of R990 and R995, connected between -300 volts and ground. The cathode circuit of V30 and V31 consists of

R996 in series with the parallel combination of R997 and C938, to ground through R991. Part of the voltage developed in the cathode circuit of this stage is applied to R977 through one of four resistive branches, depending on the position of sweep selector switch S923. The amplitude of the degenerative feedback voltage is an inverse function of the amount of resistance in a branch, and therefore, with increasing range sweep lengths, a decreasing amount of resistance is selectively inserted. Thus, in this manner, sweep amplitude is made compatible with sweep length. The low impedance sweep signal obtained in the cathode output circuit of synchro driver 29 is supplied to the rotors of both PPI and cursor resolvers 31 and 32 depicted in FIG. 4c.

A cursory consideration of the deflection circuits portrayed in FIG. 4c and FIG. 4h will reveal that four deflection channels are in evidence. The schematic circuit arrangement therein depicted consists of a N-S and E-W push-pull deflection circuit which together drive the windings of L907. Thus, as hereinbefore stated with respect to the functional block diagram of the instant invention, synchro resolvers 31 and 32 convert the sweep signal into N-S and E-W components. These are directly applied to the N-S and E-W inputs of switch stages 34 and 35, and N-S and E-W inputs of cursor switch stages 36 and 37 as indicated in FIG. 4c. Since the stator windings of each synchro are located electrically 90° apart, the sweep voltages induced in these windings will vary in such a manner that a two-phase signal is produced. Each terminal of each stator winding is used to supply a sweep signal to one of four deflection channels, affording a push-pull arrangement by virtue of the fact that the polarity of the voltage at one terminal is 180° out of phase with the other terminal. The cathodes and anodes of these stages are alternately connected as indicated to accommodate sweep voltage of both positive and negative polarity, as would be normally experienced during presentation of the sweep traces. Resistors R55 and R56 function as loading resistors for the N-S stator winding of synchro resolver 31, and in this respect, they are exemplary of the function performed by R53—R54, R61—R62, and R63—R64. The junction of grid resistors R49, R52, R60 and R67 is tied to the PPI side output of switch gate generator 47. In a comparable manner, the junction of R50, R51, R58 and R59 is tied to the cursor side output of the switch gate generator through contact d of K302 when closed, but when otherwise open as portrayed, the junction is supplied a —300 volt cutoff bias through R361 depicted in FIG. 4d. Thus, the circuit arrangement provides for expedient selective insertion of N-S and E-W components of sweep signal into push-pull deflection amplifiers 38 and 39, the respective coupling therefor being provided by capacitors C943, C955, C979, and C985. During the cursor time interval in which either a cursor sweep or a circular pattern is displayed these capacitors are charged to the slewing level potential upon appropriate gating of the cursor switch stages 36 and 37. During the PPI time interval these capacitors present a low impedance, providing a zero clamping level for the PPI sweeps upon appropriate gating of PPI switch stages 34 and 35. The circuit elements for performing this specific clamping function will be discussed presently.

Slewing cathode followers 83, 84, 85 and 86 and PPI and cursor gated clamp stages 41, 42, 43 and 44 are concerned with the selective application of cursor and circle slewing potentials, the latter including sinusoidal components, to the deflection amplifier stages 38 and 39. The slewing cathode followers comprise dual section triodes V22, V23, V24 and V25 which are responsive to the N-S and E-W signal potentials present at the contacts of K301. These stages have their elements in parallel connection to increase their current carrying capacity. The load resistors for each of these stages, V22, V23, V24 and V25, are R809, R810, R811 and R812, respectively, the common junction of the resistors being connected to a —300

volt source. The anodes of these stages are connected directly to +300 volts. Thus, the respective low impedance N-S and E-W signal potentials developed across these cathode load resistors will be the specific inputs to the respective cursor gated clamp sections proper of the PPI and cursor clamp stages 41, 42, 43 and 44.

The circuit elements herein pertinent with respect to clamping during the cursor time interval are V26, V27, V28 and V29 which are also dual section triodes in which the anodes and cathodes thereof are alternately connected to accommodate signals of both negative and positive polarity. The grids of each of these envelopes are tied together and connected to a grid resistor. Specifically, these include R802, R804, R806, and R808 which have a

common junction with cathode resistor R820, the latter functioning to supply a gating signal during the cursor time interval. In the absence of a gating signal, V26, V27, V28 and V29 will be cutoff by virtue of —300 volts supplied the above grid resistors through R820. Conversely, the appearance of a gating potential developed across R820 will render these stages conductive to thereby provide coherent clamping at the level of the incoming slewing potential. The cursor switch stages 36 and 37 are also rendered conductive during the cursor time interval and present a very low impedance in the respective charging paths for capacitors C943, C955, C979 and C985. These capacitors will charge to substantially the peak value of the applied input voltage appearing across R809, R810, R811 and R812 due to the short RC time presented in each of the charging paths. It should be noted that the signal potentials present across the respective resistors denoted may be either in the nature of exclusive D.C. signal potentials, or D.C. slewing levels combined with sinusoidal voltage components, depending on the disposition of the contacts of relay K301. Thus, in the manner specified, gated clamping of both the cursor sweep and circular pattern display is achieved at the level of the applied slewing voltage during the cursor time interval.

In a similar manner the PPI gated clamp tubes V916, V924, V944 and V949 provide synchronized clamping of the radar PPI sweeps during the time interval when the PPI sweep traces are displayed. It is to be noted in this instance that the clamping level is maintained at zero potential by virtue of the grounded input connection provided in each of these stages. In all other aspects, the electrical connections are comparable with those of the cursor gated clamp stages. Grid resistors R801, R803, R805 and R807 are tied together at one end to form a common junction, which is connected to R816 of the PPI driver cathode follower 55. Thus, the application of gating signal from the latter stage raises the grid bias of V916, V924, V944 and V949 sufficient so that conduction occurs, coincident with conduction of the PPI switch stages 34 and 35. Due to the grounded input connection, capacitors C943, C955, C979 and C985 maintain clamping of the PPI sweep signal at a zero reference level, insuring the start of the PPI traces to be always initiated from the center of the screen. The respective outputs of the PPI and cursor gated clamp stages 41 and 42 are joined in common electrical connection of the N-S channels of the push-pull deflection system. Similarly, PPI and cursor gated clamp stages 43 and 44 are joined in common electrical connection of the E-W channels of the push-pull deflection system.

PPI and cursor gate amplifier 87 functions as a phase inverter and comprises a dual triode V909 having its grids joined together and tied to the junction of R815 and R817, a fractionating signal-bias network connected between a —300 volt source and the output of V907B of the multivibrator gate 26, shown in FIG. 4g. V909 is thus rendered cutoff except during positive excursions of the applied square wave voltage from V907B. Separate in-phase outputs are developed across plate load resistors R818 and R819, which are the signal input sources for PPI driver cathode follower 55 and cursor driver cathode follower

56, respectively. The grid of pentode V908 is tied to the junction of R813 and R814 which constitutes a voltage divider with R818, providing the requisite signal and bias level for this stage. Its screen grid is connected to the PPI side output of switch gate generator 47 to thereby render V908 receptive only during positive excursions of the applied gating pulse. Since this positive excursion is of a relatively long duration, being of the order of about 30 milliseconds, cathode load resistor R816 develops an output which is a replica of the input except during such intervals when the excursion swings negative for a period equal to one radar trigger cycle, cutting off V908. The character of the gating signal obtained across R816 is indicated in FIG. 5 by waveform G.

Pentode V11 of the cursor driver cathode follower 56 is biased similarly by a voltage divider comprising R800 and R363 along with R819 through contact C of K302 in the Down position of the armature. Its screen grid is connected to the cursor side output of switch gate generator 47 to thereby render V11 receptive only during the cursor time interval. The output voltage developed across cathode resistor R820 of V11 has the characteristic appearance indicated by a waveform H in the timing chart of FIG. 5. Its generation must be considered with contact c of K302 assumed initially in one position and then in its alternate position. In the Up position of the armature of K302 as indicated in the view of FIG. 4d, the signal excitation being supplied from R819 is disrupted, and the grid and screen grid of V11 are tied together through R362 and contact c to effect a common signal input to this stage. The positive excursion of the gating voltage being supplied from the cursor side output of generator 47 is now applied to both elements of this stage and causes the production across R820 of a positive pulse, which has a duration equal to one radar cycle. On the other hand, in the Down position of the armature, contact c provides continuity to plate load resistor R819. A portion of the signal voltage developed by this resistor is dropped across R363, the remainder being supplied solely to the grid of V11. Coherent application of the gating pulse from the cursor side output of switch gate generator 47 to the screen grid of V11 in this instance will permit a positive pulse to be developed across R820, the duration of which is decided by the pulse length of the applied grid signal. Thus, in this instance, a pulse is produced having a duration which is equal to one-half of a radar trigger period. A full cycle of the voltage appearing across R820 of V11 is represented by waveform H in FIG. 5.

The N-S and E-W deflection amplifiers 38 and 39, respectively, are of a conventional type, utilizing a shielded lead input in the respective stages thereof to prevent introduction of stray signals. Balance potentiometers R123 and R1165 are provided for adjustment in circularity in the rotating sweep presentation. Inductance L907 comprises an inductive yoke having windings, L907a—b—c—d, which are quadrantly disposed in conventional manner about the neck of the cathode ray tube as portrayed in FIG. 4h, and function as the terminating load for the deflection amplifier. A representative signal input to stages V917, V925, V945 and V950 is indicated by waveform K in FIG. 5. With respect to schematic showing of the cathode ray tube 45, the accelerating and high voltage potentials therefor are merely indicated.

The detailed schematic circuits presented in FIG. 4e are those of the count-down multivibrator 46, the switch gate generator 47, the relay driver 56, and the time shared brilliance and blanking circuit 48. The count-down multivibrator 46 comprises stages V4, V5, and V6 which collectively function to ignore a certain number of square wave signals from V907A, responding to one predetermined by the setting of R30. The applied waveform is initially differentiated by the RC network C12 and R20 and impressed onto V4A, which operates as a trigger amplifier biased near cutoff. Only the positive trigger or spike portion of the differentiated waveform

is therefore significant. An amplified inverted trigger appears across plate resistors R23 and R2609. To visualize the operation of the count-down multivibrator circuit, assume that no triggers are arriving to the input of the trigger amplifier. The static conditions which prevail in the absence of signal excitation are as follows: C15 is charged to +110 volts which is impressed onto the grid of V6B, causing plate current flow through this section. V6A is cutoff by virtue of the bias developed across the common cathode resistor R29. Anodes and cathodes of diode gate V5 are maintained at very nearly +300 volts. Cathode follower V4B is conducting. Hence, initial application of a negative trigger to the cathodes of V5 will cause appearance of this voltage at the grid of V4B, causing the voltage across R24 to follow. Concurrently, with the appearance of the negative potential across R24, C15 discharges through this resistance, initiating cutoff of section V6B and conduction of V6A. The reduced plate voltage of V6A now blocks the passage of succeeding triggers through diode gate V5 until such time when V6B is precipitated into conduction by the ninth trigger. The elapsed time is precisely controlled by the setting of R30, which forms a part of the charge path for C15. The character of the voltage at the grid of V6B and at test jack J1 is as shown at L and M in FIG. 5, respectively.

Switch gate generator 47 is of the type described in copending patent application Serial No. 637,602 and comprises dual, triodes V7, V8 and V10 in a symmetrical cathode coupled arrangement as illustrated in FIG. 4e, producing a bistable voltage of the form indicated by the waveforms E and F in FIG. 5. Capacitor C16 and resistor R34 differentiate the output waveform of V6B, the differentiated signal initiating change in the bistable state of switch gate generator 47 in synchronism with the leading edges of the applied differentiated waveform. Waveform O in FIG. 5 is representative of this excitation. The cathode output of V8 and V10 is designated specifically as the PPI and cursor side outputs, respectively, which complementally vary between limits of +110 and -240 volts.

Relay driver 56 bears structural and operational resemblance to switch gate generator 47, and therefore, only a cursory discussion is deemed necessary. As its appellation implies, relay driver 56 is employed to alternately drive into actuation relays K301 and K302, in response to the bistable voltage from the PPI side output of switch gate generator 47. The leading edge of this voltage is differentiated by the action of C17 and R393 and applied to the anode of a diode clipping stage V315. The anode of this stage is tied to a positive potential point at the junction of R392 and R394, which with R391 and R395, comprise a voltage divider connected between -300 volts and ground. Only the positive portion of the differentiated waveform is significant to effect change in status of relay driver 56. The bistable voltages which are produced across R385 and R388, respectively, are of opposite phase with respect to each other and have a recurrence rate of 15 cycles per second. These voltages are representatively portrayed by the waveforms P and R in FIG. 5. The cathodes of V313A and V313B are each connected through dropping resistors to the coils of relays K301 and K302, respectively, which thus function in a complementary manner, that is to say, the respective armatures are made to differentially actuate in direct response to the application of the voltage waveforms depicted in FIG. 5. Capacitive elements C345 and C346 are bypasses serving to discharge the inductive current of the relays during transitional operation of the relays.

The time shared brilliance and blanking circuit 48 may be best described with relation to waveforms D, E and F portrayed in FIG. 5. V20 is a dual section triode type 2C51 which functions as a blanking stage and has its elements paralleled. The grids of this stage are con-

nected to multivibrator gate 26 which supplies the square wave voltage represented by waveform D. V21 is also a type 2C51 and functions as a sweep-cursor brilliance stage, the grids thereof being respectively connected to separate voltage dividers as indicated in FIG. 4e. The lower ends of R68 and R69 are connected to a -300 volts supply; the other ends of the dividers are respectively tied to the PPI and cursor side outputs of switch gate generator 47. Thus the bias presented V21 complementally varies in a manner representatively portrayed by waveforms E and F, causing the plate current to be cutoff in one section and permitting it to flow in the other. Potentiometers R96 and R97 are the cursor and sweep brilliance controls, respectively, and are effective in each instance to control the amount of gate injection. R65 is a common cathode resistor for V20, V21 and CRT45. With respect to the specific operation of the time shared brilliance and blanking circuit 48, it will be evident that positive blanking pulses of a sufficient magnitude developed across R65 will bias the CRT to cutoff. Thus, with applied excitation as herein denoted, the composite plate current flow through these stages produces about 50 volts across R65, which is sufficient to block the flow of beam current in the CRT for a duration coterminous with the positive portion of waveform D. During the negative portion of waveform D, V20 is cutoff, and the reduced potential across R65 now permits the CRT to be unblanked or intensified during the precise time interval when either a circular pattern, cursor or PPI sweep is being presented. Thus, time shared intensity modulation of the cathode element of CRT45 in the manner described provides for selective presentation of the radar PPI sweeps, cursor and circle.

Referring next to FIG. 4h, the video channel therein illustrated is of an existing type used with the radar set which incorporates the instant invention and has been modified to permit signal injection on a time shared basis. The positive video signal applied at terminal 49 is amplified and inverted by video amplifier 51, appearing across a plate load network consisting of R1116 and L909. The inverted video signal is capacitively coupled into video switch stage 52, in the grid circuit of which the video signal is clamped by V938 in conjunction with R1119 and C970. V937 is of a pentode type having its screen grid tied to the PPI side output of switch gate generator 47. This stage normally conducts during application of the positive portion of the applied square wave, but is otherwise turned completely off during the cursor interval when the screen grid is negative with respect to the cathode. Strobe switch 53 acts as a grounded grid amplifier, and serves to inject during the cursor interval a positive strobe voltage selectively available at contacts a-b of relay K302. The screen grid of pentode V9 is connected to the cursor side output of switch gate generator 47, and therefore, it will be apparent that plate current flow through either V9 or V937 occurs in a reciprocal manner. Both switch tubes utilize a common resistive load R1120, with the result that signals amplified by either tube are routed via LC shunt peaking elements L910 and C971 to cathode follower 54. The grid of V9 is connected to the wiper arm of video compensation control R99, allowing the grid of V9 to be varied over a range of negative potentials through its connection to the -300 volt supply. In this manner, the video compensation control permits adjusting the plate current flow of V9 during its "On" time, to exactly equal the plate current of V937 during its "On" time. In this way the baseline of the video waveform is maintained at a constant level. As a result of the switching actions of these stages, either video or strobe voltage appears at the input of cathode follower 54. This stage utilizes a pentode V939 having shunted across its grid circuit a diode clumper V904A, assuring thereby positive signals at the grid of V939. The low impedance signal developed across gain potentiometer R1130 is capacitively cou-

pled by C972 to the grid of the CRT. As in the previous instance, a clumper V940B is employed to remove any averaging of the signal, as a result of C972. Potentiometer R1133 is a part of the resistive voltage divider connected between ground and the -300 volts supply, and functions as a normal brilliance control, serving to control the beam current of the cathode ray tube. Thus, in the manner described, the inventive intercept computer provides for the time shared insertion of radar video and strobe voltage, the latter being manifested on the PPI screen either as the cursor dot S or azimuth circle dot D, previously denoted.

FIG. 4a depicts a detailed electrical circuit of the sine wave oscillator 57 and a schematic showing of the timing mechanism 90 discussed in connection with FIG. 2. Oscillator 57, employing a parallel-T frequency sensitive network 88, is designed to supply a constant amplitude voltage at approximately one kilocycle frequency. V301 and V303A are electrically connected through network 88 to provide sustained oscillations at a fixed frequency, while the dual triode section of V302 is used in a regulation circuit to maintain a constant voltage output of the oscillator. Negative bias for the grid of V301, a pentode, is obtained through R301 from a divider consisting of R302, R342, and R343. R303 functions as a plate load whose sinusoidal signal is directly coupled to V303A, which basically functions as a cathode follower. A potentiometer R308 having a small value of the order of 1K ohms in the plate circuit of V303A develops a positive feedback voltage of sufficient magnitude and required phase relation to sustain oscillations at the grid of V301. The circle time potentiometer R13 forms a part of the cathode load resistance for this stage with R311. In order to provide a very stable voltage across potentiometer R13, the full cathode voltage of V303A is capacitively coupled through V302B, which has its grid and anode joined together forming a diode rectifier. Its load impedance consists of potentiometer R310 and capacitors C303. The wiper on R310 provides for a portion of the D.C. voltage developed across this impedance to be applied to the grid of section V302A, control R310 thus acts as an oscillator amplitude control. V302A operates as a D.C. amplifier having a plate load resistance R304 which is also the screen dropping resistor for V301. Hence, it will be apparent that any variation in the oscillator voltage at the cathode of V303A will be reflected as a change in the D.C. level at the grid of V302A. The screen potential of V301 varies accordingly, to effect change in the transconductance of this stage, and consequently, the oscillator voltage output is modified in inverse relation to the variation which initiated the regulatory action.

The sinusoidal voltage available at the wiper of circle time potentiometer R13 is the analog of time, either elapsed or future. This analog voltage is capacitively coupled by C308 through a divider comprising R312 in parallel with C309, R313, and R314 as portrayed in FIG. 4b. One section of the four position switch S923f, which is a part of the range sweep selector, will be seen to selectively supply an apportioned amount of the applied A.C. voltage to cathode follower and circle speed potentiometer 58. Thus, the grid of V303 receives a signal which is compatible with the range selected. In the 20 mile position of the range sweep selector, it will be observed that the intercept computer is effectively electrically disconnected. No attempt is made to compute a target intercept point in this range position because of the very short flight time involved. A low impedance replica of the input signal appears across interceptor speed control potentiometer R90, which in the instant invention is linearly calibrated from 0 to 600 knots. As hereinbefore stated, this potentiometer is preset in accordance with the predetermined speed of the interceptor aircraft. It is of transcendent importance to observe that since the A.C. voltage developed across R90 varies directly with

time, the voltage at the wiper now represents distance. This voltage is capacitively coupled through C312 and is presented across load resistor R323. Hence, the multiplication process is consummated.

The voltage proportional to distance is impressed on the 90° phase shift network comprised of C310—R317 and C313—R324, which produce leading and lagging phases, respectively. The value of these elements has been selected so that the respective RC combinations provide phase shifts of $\pm 45^\circ$. Thus, with respect to the grids of V304A and V304B, the first stages of a cascade push-pull amplifier 59, the relative phase relationship therebetween is 90°, as required in a circular Lissajous pattern generation. R317 is a potentiometer, which permits phase correction, thereby assuring a phase shift of exactly 90°. Stages V305A and V305B are fed the signals in quadrature phase relation and amplified versions thereof are supplied to the A.C. and D.C. component mixer 61. A small amount of current feedback is provided to improve the stability characteristics of the amplifier. R316 in this respect supplies a fixed amount of current feedback, while R327 is variable, providing for controlled feedback. Since the amount of degeneration directly affects the gain of an amplifier, R327 also functions as a circularity control.

The sinusoidal voltages developed across plate load resistors R396 and R329 are simultaneously applied to the associated primary windings of transformer T301 and T302, respectively, which comprise elements of the A.C. and D.C. component mixer 61. The respective secondary windings of these transformers are center tapped, which points are grounded as shown in FIG. 4b. Therefore, the A.C. voltages in quadrature phase which are applied to the primaries of these transformers will produce in the respective center tapped secondaries thereof components of circle information. Thus, the push-pull arrangement herein set forth provides the requisite N-S and E-W components of A.C. voltage of a correct phase for generation of a circle. These components are capacitively coupled into the respective channels of the deflection system through C322, C323, C325, C326, and the *a—b—c—d* contacts of K301 in the down position of the armature as indicated in FIG. 4b. A shorting switch S303 is supplied to effect zero A.C. output from transformers T301 and T302 during calibration adjustments. The elements completing the circuit of the A.C. and D.C. component mixer 61 include capacitive input RC filters, which specifically are C318—R338, C319—R339, C320—R340, and C321—R341. Each of these RC combinations are interposed in the N-S and E-W signal leads between circle position circuit 63 and the sinusoidal component voltage outputs of T301 and T302. Hence, the specific circuit arrangement permits superimposing the aforementioned sinusoidal components onto D.C. reference levels, the generation of which will be discussed next.

Circle positioning circuit 63 is electrically similar to the cursor positioning circuit 65, differing only in application. With respect to circle positioning circuit 63, the respective voltages generated as a function of the displacement of joystick 62 are applied directly to the aforesaid RC combinations as indicated in FIG. 4b. Similarly, the cursor displacement voltages are applied to the deflection channels through the *a—b—c—d* contacts of K301 in the up position of its armature. In view of the similarity of these circuits, only the cursor positioning circuit will be specifically discussed. Hence, as portrayed in FIG. 4b, joystick 64 is denoted as being mechanically linked with four potentiometers R91, R92, R93 and R94. R91 and R92 are varied when the stick is moved in a N-S direction and R93 and R94 are varied when the stick is moved in an E-W direction. The pairs of potentiometers are mechanically interconnected by a conventional gear and linkage mechanism, not herein illustrated, so that the stick can be moved freely in any direction to thereby effect positioning of the cursor line. Specifically, a divider network

consisting of R70 and R71 is connected between +300 volts and ground. Its mid-point is connected to one side of each pair of potentiometers. Another divider network consisting of R72 and R73 is connected between -300 volts and ground with its mid-point connected to the other side of each pair of potentiometers. Hence, within the limits of the values of the resistive elements comprising the network set forth above, a definitive potential range is established over which the potentiometer wipers are able to pick off any voltage within this range. A mechanical connection has been so arranged that when the stick is pushed north, one of the N-S potentiometers increases positively and the other negatively. The same holds true for the E-W potentiometers. Capacitors C327, C328, C329 and C330, connected in the manner shown in FIG. 4b, shunt to ground any ripple voltage picked up on the relatively long wires from the joystick. Thus, the slewing voltage outputs associated with joystick 64 are used to position the origin of the cursor line on the screen of the PPI scope. In comparable manner, the slewing voltage outputs associated with joystick 62 position the circular trace.

Referring next to FIG. 4d, the circuits therein particularly illustrated are those of the cursor speed potentiometer 25 and cathode follower 73, D.C. amplifier 75, the phantastron cathode follower 77, phantastron 78, delayed trigger amplifier 79, and blocking oscillator 81. These circuits relate to the generation of a range strobe, or more specifically the cursor dot S, in accordance with the multiplication process of the instant invention. It is to be noted that these circuits exist in part in the indicator of the radar set incorporating the instant invention, and therefore, the range strobe may be selectively employed either in exclusive radar search operation or in application during an intercept problem. The particularized showing of these circuits is deemed desirable for proper system correlation with regard to the newly introduced time sharing cursor circuitry. With respect to the illustration of the circuits in FIG. 4d, the signal input for cursor speed potentiometer 30 and cathode follower 73 is derived from the cursor time potentiometer R14, which has applied across it approximately 240 volts by virtue of its connection at one end to a negative reference point at the anode of voltage regulator tube V308 and R348, and at the other end to the +300 volts supply through R346. A dual section triode V306 is employed having in its cathode circuit a delta biasing connection, one arm of which comprises a cursor speed potentiometer R80. A potentiometer R348 of a relatively small value compared to R349, a 300K resistor, is used as a balance control, the wiper thereof supplying the proper bias to the grid of V306B. The voltage developed across the cursor time potentiometer R14 between the negative reference point and the instantaneous position during travel of the wiper is the analog of time, either elapsed or future, as was the case with the circle time potentiometer R13. This analog voltage is applied to the grid of V306A and appears as a potential difference across the cursor speed potentiometer R80. There exists a point on this potentiometer during an intercept operation wherein the rate of change of the potential level between the wiper and the lower junction of R350 and R351 is coincident with the target displacement, when observed on the screen of the PPI scope. Thus, multiplication of target speed by time is achieved. The aforesaid voltage proportional to distance is impressed onto the grid circuit of V307A of D.C. amplifier 75 through R352. V307A functions as a cathode follower while V307B operates essentially as a grounded grid amplifier having its D.C. signal developed across R353. Potentiometer R355 connected in a voltage divider circuit as shown in FIG. 4d permits adjustment in bias for V307B and functions as a slope gain control. Potentiometer R359 also connected in the voltage divider circuit is used as a zero set control to facilitate calibration of the cursor dot with the start of the cursor trace. In operation, any change in the D.C.

level at the grid of V307A will appear as a potential change across R356. Consequently, change in the grid to cathode potential of V307B is effected, and an amplified version of the original signal appears in the plate circuit. This voltage level proportional to distance is fed through a selector switch 76 associated with the phantastron cathode follower 77.

A range-delay potentiometer R917 is indicated in FIG. 4d as a part of a voltage divider connected between ground and +300 volts. A slope and a zero set control, R916 and R919, respectively, are employed to facilitate range calibration in conjunction with the normal presentation of PPI radar sweeps. It will be observed that the selector switch 76 in the radar position applies the voltage associated with the wiper of R917 to the cathode of V903A, accommodating normal target ranging during radar search operation. In the computer position, the voltage analogous to target distance is alternatively applied to V903A from D.C. amplifier 75. With regard to the phantastron action embracing both the cathode follower 77 and phantastron 78, only a cursory discussion of these stages is deemed necessary in view of their recognition in the radar art. V903 is a dual section triode having its left half section employed as a diode, and its right half section employed as a cathode follower. Phantastron 78 utilizes a type 6BE6 tube, having an output which is taken across cathode resistor R928. It should be noted that this output is a square wave voltage having a leading edge which may be delayed an amount proportional to the amplitude of the potential level at the cathode of V903A. During quiescent operation, both halves of V903 are conducting and V904 has its plate current cutoff by virtue of screen current flow through R928. Concurrently with the application of a positive potential level to the cathode of V903A, a negative trigger is supplied from the transmitter pulse cathode follower 25. This action results in a negative trigger being developed across R927, causing the fall of potential across R924. This fall of potential is capacitively coupled through C908 and C909 to the grid of V904, reducing momentarily the cathode current through R928. A reinforcing feedback action follows which drives the grid of V904 to its lowest negative level, which thereafter begins to rise toward +300 volts. The rise would normally be exponential except that the use of cathode follower V903B permits a linear rise of grid potential. Consequently, a linear increase of plate current occurs simultaneously with the linear decrease of screen current, and in the cathode circuit of V904 a constant voltage drop results. When plate current reaches a value such that it no longer feeds back a sufficient negative signal to the grid, grid voltage rises very rapidly. At this point, the screen grid current increases, and causes the current through R928 to produce a large voltage drop across this resistor. This drop is applied to the suppressor grid, and is of sufficient amplitude to result in plate current cutoff. The plate voltage at this time rapidly rises to a value determined by the conduction through both triode sections of V903. Thus, a square wave is produced in which the leading edge thereof may be delayed a proportional amount according to the D.C. input level appearing at V903A. This square wave voltage is applied to the grid of V905A, the first triode section of delayed trigger amplifier 79. The time constant of the grid circuit, principally determined by C905 and R934, is very short, with the result that the leading and trailing edges of the square wave are differentiated, and a negative pulse and a positive pulse are produced. V905A is biased beyond plate current cutoff by a fixed bias from a voltage divider consisting of R942, R943, and R944, which is connected between the -300 volt supply and ground. Since the tube is beyond cutoff, the negative pulse is not reproduced in the plate circuit. The positive pulse, however, causes momentary conduction through the tube, thereby producing a drop in the plate voltage. A peaking coil L902 is in series with the plate load resistor R935 to increase the

sharpness of the drop produced in the plate circuit. The negative pulse from the plate circuit of the first triode section is applied to the second triode section through capacitors C911. Normally, V905B is in a state of conduction, and the application of the negative pulse to the grid of this section results in its reproduction in the plate circuit. A peaking coil L903 is also included in the plate circuit of V905B to increase the sharpness of the pulse.

The positive pulse output of delay trigger amplifier 79 is applied to capacitor C912, to the grid of V905A of conventional blocking oscillator 81. Normally, V906 has both triode sections biased beyond plate-current cutoff, by application of a fixed negative voltage to the grids, of approximately -15 volts. As for the delayed trigger amplifier 79, this bias voltage is also obtained from the voltage divider consisting of R942, R943, and R944. The first triode section V906A serves only to initiate the operation of the second triode section V906B. The application of the positive pulse to the grid of V906A causes plate current to flow for the duration of the applied positive pulse. The plate current flow causes a positive voltage to be induced in the grid winding of transformer T901, implementing a feedback cycle and the development of the positive voltage across cathode resistor R940. When T901 reaches saturation, plate current decreases in both sections of V906, and this stage is rapidly driven beyond cutoff, again resuming its quiescent status. The positive spike voltage across R940 is made available for insertion into the video channel at the lower parallel a-b contacts of relay K301 through a semi-conductor diode CR302, which herein functions to block the passage of any attendant negative transients during transitional operation of relays K301 and K302. Hence, a cursor dot or range strobe is developed, its displacement on the screen of the PPI scope with respect to the instant invention being a function of the constant speed rotation of cursor time potentiometer R14 and the position of the wiper on cursor speed control potentiometer R80.

Finally, with respect to FIG. 4f, there is illustrated in particular a cascode resolver driver 66, an azimuth circle control resolver 68, a phase shift mixer 69, and an azimuth dot generator 71. The purpose of these circuits is to convert the reference sinusoidal voltage obtained from oscillator 57 into a spike voltage which is presented on the screen of the PPI scope as the azimuth circle dot D superposed onto the circle and movable about its periphery. In this manner, intercept headings taken from a stabilized north reference may be accurately predicted. Consonant with this objective, cascode resolver driver 66 comprises a dual triode V310, which is used as a specialized cathode follower of exceedingly low output impedance. Its upper section V310A is capacitively coupled through C335 to a divider consisting of R364 and R365, which is connected between the output of oscillator 57 and ground. R368 fixes the bias for this stage as in conventional cathode bias. The lower section V310B is utilized as the load across which a low impedance magnified version of the input signal voltage is developed. This voltage is capacitively coupled by C337 to the rotor of a two phase resolver 68. Since the stator windings of this resolver are in a quadrature phase relation with respect to each other, the respective voltages electromagnetically induced therein represent components of the rotor voltage, the amplitude thereof being a function of the angular displacement of the rotor. Hand-wheel 67 is mechanically coupled with the rotor and an intercept heading dial 82, which is calibrated in degrees from a north reference point. Capacitors C338 and C339 are supplied to resonate the respective stator windings. The latter are joined at one end forming a junction which is grounded, as indicated. The A.C. voltage taken at the outer extremities of the stator windings is applied to a phase shift mixer 69 comprising C340, R372, and a phase adjust potentiometer R371. The phase shift mixer recombines the voltage components

supplied to it and presents at the junction of C340 and R372 a single sine wave voltage, the phase of which may be shifted by the handwheel over a 360° range.

The output of the phase shift mixer 69 drives the azimuth dot generator 71, which comprises a two stage amplifier clipper and a blocking oscillator similar to blocking oscillator 81. The positive portion of the sinusoidal signal presented to V311A undergoes grid clipping by virtue of grid resistors R373 as is also performed by R376 in the grid circuit of V311B. The substantially square wave output voltage developed across R375 is then differentiated in a RC network consisting of C342 and R378. Due to the bias voltage imposed on the grids of the blocking oscillator stage which immediately follows, the negative triggers have no significance. Only the positive differentiated triggers are thus effective to initiate operation of V312. The latter stage is in all respects similar to blocking oscillator 81, and functions to produce a single sharp trigger across R379. The trigger thus generated is positionable over a 360° range by means of the manual crank 67 and is made available through a semi-conductor diode CR301 at the upper a—b contacts of K301 for insertion into the video channel.

An approach to the electrical system operation of the inventive interceptor computer may best be set forth with relation to the timing chart of FIG. 5 wherein the relative amplitude and phase relationship of the various waveforms are indicated. With respect to the particular manner in which time sharing is performed in the instant invention, four distinct modes of operation exist. A basic mode of operation involves the normal presentation of PPI radar sweeps, followed by a mode of operation in which a circular pattern is presented, followed again by presentation of PPI radar sweeps, and succeeded lastly, by the cursor mode of operation. The ratio of presentation of PPI radar sweeps to either the cursor or circle as hereinbefore mentioned is nine to one. Consider initially the mode of operation wherein the radar PPI sweeps are applied during an interval embracing substantially the first eight radar triggers and in which the differentially operative relays K301 and K302 have their contacts disposed as portrayed in FIG. 4, the composite electrical schematic drawing of the instant invention. Lower contact d of K302 is in the open position, permitting a cut-off bias to be supplied to the grids of the cursor switch stages 36 and 37. A -300 volts will be supplied through R361 to the junction of R50, R51, R58 and R59. Conversely, PPI switch stages 34 and 35 are in a conductive state by virtue of application of the PPI side output voltage depicted by waveform E, which is of a positive polarity during the internal herein considered. The screen grid of V908 of PPI driver cathode follower 55 also receives this positive voltage, conditioning this stage for operation. A square wave voltage from multivibrator gate 26, depicted by waveform B, is continuously supplied to the grids of V909, which is employed as an inverter. A replica of the signal, inverted in phase, may now be taken as that represented by waveform D, and appears in the grid circuit of PPI driver cathode follower 55, which conducts on positive excursions of the applied square wave. A positive gating voltage, developed across R816 is supplied to the grids of the triode gating clamp tubes V919, V924, V944, and V949. Waveform J is exemplary of this voltage during the interval encompassing the first eight triggers. A comparison of the phase relations between the waveform J and sawtooth waveform C will indicate that the positive excursions of waveform J immediately precede the start of the sawtooth sweep voltages. Consequently, during this blanked-out interval the above-mentioned triode clamp tubes present a very low impedance and one end of each of the capacitors C943, C955, C979, and C985 may be momentarily considered effectively at ground potential. Hence, the sweep input to N-S and E-W push-pull deflection amplifiers 38 and 39, respectively, is clamped

5 at ground potential prefatory to the start of each radar PPI sweep trace. Thus, in the manner described, push-pull sawtooth deflection voltages are applied during the PPI interval to the CRT so long as PPI switch stages 10 34 and 35 are conditioned by the positive level of voltage waveform E, and further, the gating clamp means provided permits the sweep traces to be initiated from the center of the CRT. The remaining contacts of K301 and K302 are not pertinent during presentation of the normal radar PPI sweep traces.

15 Referring next to the mode of operation in which the circular pattern is developed on the screen of the PPI scope, assume that the eighth trigger has occurred and that the respective armatures of K301 and K302 are disposed as indicated in response to the voltages represented by waveforms P and R. Contacts a—b—c—d of K301 provide four channel continuity between the output of A.C. and D.C. component mixer 61 and the input of the slewing cathode followers 83, 84, 85, and 86. Hence, the N-S and E-W sinusoidal voltage components, superposed onto respective D.C. reference levels each having a magnitude and polarity determined by the displacement of joystick 62, are impressed onto the slewing cathode followers. A low impedance replica of each of the sinusoidal unidirectional N-S and E-W voltage components is developed across cathode resistors R809, R810, R811 and R812, which form the resistive load inputs to the triode gated clamp tubes V26, V27, V28 and V29, respectively. The latter stages are gated by voltage waveform H, which is positive during the interval herein pertinent between 8.5t and 9.5t, considering waveform A as the timing index. Paralleled contacts a—b of K302 provide continuity between the cathode output of blocking oscillator stage V312 of the azimuth dot generator 71 and the cathode of V9 of strobe switch 53. In this manner, the specific contacts accommodate coherent presentation of the azimuth circle dot D, with the time shared display of the circular trace on the PPI screen. Contact c of K302 permits common connection of the grid and screen grid of VII through R362, effecting triode operation in which the excitation for the combined elements thereof stems from the cursor side output of switch gate generator 47. Contact d of K302 is open, permitting full cutoff bias to be applied to the switch stages 36 and 37 to thereby prevent insertion of a cursor sweep at this time. With respect to the PPI driver cathode follower 55, it will be observed that the coincident application of voltage waveform E and a square wave voltage as that depicted by waveform D to the screen grid and grid of V908, respectively, will produce plate current cutoff, and accordingly, a fall in cathode potential for a duration approximately equal to one and a half trigger recurrence periods. This voltage is exemplarily portrayed by waveform G, the pertinent negative portion occurring in the interval between 8t and 50 9.5t. Hence, the application of the voltage of waveform G to the grids of V916, V924, V944 and V949 during the indicated time interval will render these triode gated clamp tubes cutoff, effecting removal of the low impedance paths previously afforded by these stages during presentation of PPI radar sweeps. With respect to V11, its cathode output is denoted by waveform H whose positive portion is coterminous with the time interval between 55 8.5t and 9.5t. Therefore, clamp tubes V26, V27, V28 and V29 will now conduct, being responsive to the applied unidirectional sinusoidal voltage components in the respective inputs of these stages. Direct coupling is thus provided into the push-pull amplifier 38 and 39. Since the sinusoidal components appearing at the respective inputs of the deflection channel are in quadrature phase relation, quadrature A.C. currents flow in yoke L907 and a circular trace is produced on the PPI screen, in accordance with Lissajous' pattern generating concepts. The displacement of this circle from the center of the screen is determined by the polarity and magnitude

of the D.C. components, generated as a function of the displacement of joystick 62. This mode terminates at 9.5*t*, at which time various circuits recycle preparatory to returning to the PPI mode of operation. Of particular significance, relays K301 and K302 complementally actuate in response to the square wave drive voltages P and R, whose bistable states are now reversed.

Consider next the PPI mode of operation in which the respective armatures of K301 and K302 are disposed in the opposite position from that portrayed and the sweep traces displayed are those associated with the time interval embracing the tenth through the eighteenth trigger, as shown in FIG. 5. Contacts *a*—*b*—*c*—*d* of K301 will be closed in the upward position of the armature, but as in the downward position, no function is served by these contacts during the PPI interval. However, contact *d* of K302 augments the -300 volts being supplied through R361 to the grids of the cursor switch stages 36 and 37. The bias for these stages is now a function of the applied cursor side output voltage of switch gate generator 47. The lower level of voltage waveform F is maintained at -240 volts, which is sufficient to render switch stages 36 and 37 cut off during the radar PPI interval, as before. Contact *c* previously allowed pentode V11 of cursor driver cathode follower 56 to act as a triode by tying together the grid and screen grid of this stage through R362. In the down position of the armature of K362 as now considered, the grid of V11 is electrically connected to the junction of R363 and R800, which form a voltage divider connected across the output of V909A of PPI and cursor gate amplifier 87. However, despite the separate excitations to V11, this stage is still maintained cut off by virtue of its screen grid being connected to the cursor side output of generator 47, which supplies a negative voltage level during the time interval associated with the tenth through the eighteenth trigger. Consequently, the electrical action which occurs during the aforesaid time interval with respect to the generation of radar PPI sweeps is precisely identical with the operation previously discussed when the contacts of K301 and K302 were in the position shown in the composite schematic illustration of the instant invention. Also, as before, contacts *a*—*b* of K302 which are affiliated with the selective coherent insertion of azimuth circle dot D and cursor dot S are not pertinent at this time, since strobe switch 53 is blocked at this time.

Finally, with respect to the cursor mode of operation, assume that the contacts of K301 and K302 are disposed oppositely to that shown in the composite illustration and that the eighteenth trigger has just occurred along the timing index. The slewing potentials generated by the cursor joystick 64 of cursor position circuit 65 are admitted to the slewing cathode followers through contacts *a*—*b*—*c*—*d* in the upward armature position of K301. Contacts *a*—*b* of K302 are now disposed to insert the cursor dot voltage into the video channel upon gating of strobe switch 53. Contact *c* of K302 connects the output of V909A to the grid of V11 through R363, while contact *d* augments the cutoff bias supplied to switch stages 36 and 37. The latter stages are now responsive to the bistable voltage available at the cursor side of generator 47, and present a low impedance during the interval between 18.5*t* and 19.5*t*. With respect to the cursor driver 56, the coincident application at the output voltage of V909A with the cursor side output voltage of generator 47 to the grid and screen grid of V11, respectively, will produce plate current flow in this tube only during such time when the applied signal excitation is positive. Since a disparity exists between pulse widths of the applied voltages, the voltage of shorter duration is determining, and a pulse voltage equal to about a half trigger recurrence period is developed across the cathode resistor R820 of V11. Hence, this pulse is as indicated in waveform H during the interval between 18.5*t* and 19*t* and is employed as a gating pulse, which is applied to the triode

gated clamp stages V26, V27, V28 and V29, as in previous instances. These stages are now allowed to conduct, forming a charging path for capacitors C943, C955, C979 and C985. Because of the short RC time constant involved, these capacitors are charged to substantially full value of their respective slewing potentials developed across resistors R809, R810, R811 and R812. The push-pull amplifiers 38 and 39 are responsive to the potentials appearing across these capacitors, causing the electron beam to be initially displaced according to the position of joystick 64, prefatory to application of the sweep voltage. Immediately upon cessation of the "half-gating" voltage depicted in waveform H, a cursor sweep voltage is extracted from resolver 32 by virtue of the fact that cursor switch stages 36 and 37 are still rendered conductive. Hence, N-S and E-W cursor sweep components are superposed onto the respective D.C. potentials acquired by capacitors C943, C955, C979 and C985. The nature of the composite voltage applied to an input of the deflection amplifiers is indicated in waveform K during the interval between 18.5*t* and 19.5*t* of the timing index. Thus, a cursor sweep is caused to be initiated from a point on the screen determined by the applied D.C. displacement voltages. When the sweep trace is terminated at approximately 19.5*t*, switch gate generator 47 initiates transitional operation of circuits in the intercept computer in preparation for a new cycle.

Although the system operation of the inventive intercept computer has been particularly described in relation to relay K301 and K302, the applicant's intercept computer may alternatively embody electronic switching means in lieu of the electromechanical elements herein set forth, since such electronic switching means cooperate with the other components of the system in the same manner to produce the same results as these electromechanical elements. Therefore, it is deemed that relays K301 and K302 are merely illustrative of means for achieving switching, and that the use of vacuum tubes and semi-conductor elements for performing electronic switching does not affect in any manner the spirit or scope of the instant invention.

Hence, in the manner herein described, the instant invention provides for an integrated display of circular and cursor pattern presentations in time shared relation with radar PPI sweeps. In addition, the cursor and azimuth circle dot voltages are inserted into the video channel for intensity modulation of the grid of the CRT. Thus, the visual presentations herein developed facilitate carrying out the instant invention in accordance with inventive concepts.

FIG. 6 presents a diagrammatic view of the structure comprising timing mechanism 90 heretofore schematically portrayed in relation to the electrical circuits of the intercept computer. The CW or CCW rotation of the various rotary elements in FIG. 6, as well as FIGS. 7 and 8, is indicated by appropriate arrowhead notation when these figures are viewed from the left. With respect to FIG. 6, there is illustrated in this view a constant speed motor 16, having a maximum arbitrary shaft rotation of one revolution each 30 minutes. Consistent with this design criteria, the housing proper of potentiometers R13 and R14, comprising the driven elements of a time drive system, have been chosen to rotate at the same speed relative to their respective shafts, and accordingly, the time-to-intercept indicator 18 may be conveniently graduated into 30 divisions, one minute per division. The rotation of motor 16 is transmitted through an overload clutch 153. Several slip clutches of a generally known type, designed to slip beyond a predetermined applied torque, are employed and will transmit rotation only when the applied torque is not exceeded. These include 114, 130, 145 and 155. Slip clutch 91 is of a unidirectional type, gear 92 to which it is attached may slip CCW with respect to shaft 93. Frictional brake 119 provides a drag force or damping of the gear train which is associated with it. A conventional differential 17 is provided

which facilitates modifying the relative position between the wiper and housing of both potentiometers R13 and R14 when the time modifier hand control 19 is turned, effectively modifying the chronometric output relation of the timing mechanism. Spider shaft 134 of this differential is integrally attached to shaft 140 by pin 135, permitting the spider shaft to rotate when pinion gears 133 and 137 turn at different rates. Stops 112, 127 and 142 are provided to terminate rotary motion of the gear trains respectively associated therewith. Stop 110 is a movable stop. The abutting member 110a is fixedly mounted as an integral part of the housing of potentiometer R13. Consequently, the action of the wiper portion 110b terminates at a point depending on the position of the housing of R13. Shaft 93 is designed for translation along its length, being positionable in one of two fixed positions by either pushing or pulling the time modifier hand control 19. Shaft 93 is schematically shown to be held in either position by friction, but may be conveniently maintained in place by a pressure spring, detent, or the like. Thus, the conic surface 97 and its complementary companion collar 98 constitute a cone clutch, as is also true of elements 95 and 96. An electromagnetic clutch 106 is controlled by a SPDT switch S301, which supplies excitation to either motor 16 or the clutch from a unidirectional source of E.M.F. herein depicted by battery 156. Source 156 may be conveniently the voltage of the 28 volt D.C. electrical power system of the aircraft incorporating the inventive intercept computer. Thus, the structure basically set forth provides for the chronometric rotation of potentiometers R13 and R14, together with provisions for effecting modification of the chronometric characteristics of the timing mechanism.

With respect to the operation of the timing mechanism, four modes of operation exist. These include namely the advance, retract, running, and reset modes of operation. The time mechanism running mode of operation will be discussed initially in relation with the time drive structure pertinent thereto, and illustrated in FIG. 7. Hence, in connection with this view, switch S301 is closed causing the shaft 157 of motor 16 to rotate in a CCW direction, as viewed from the left. The circuit of the motor pilot light 154 is also completed. Gear 152 imparts rotation to shaft 148 through gears 149 and 151. Shaft 148 causes rotation of the time drive system through gear 125 which turns gear 124. The case or housing of cursor time potentiometer R14 is integrally joined with gear 111; consequently, it rotates CCW as indicated relative to its wiper which is held stationary by the frictional brake clutch 119 through the gear train comprising gears 123, 122, 121 and 118. The case of the interceptor time potentiometer R13 also rotates in a CCW direction by virtue of drive gear 108 being driven away from stop 112. Its wiper is also held stationary by frictional brake 119 through slip clutch 114 gears 113, 115, 116 and 117. Thus, as the potentiometer cases rotate at a chronometric rate, the respective wipers thereof are displaced linearly with time. Shaft 48 imparts rotation of the spider shaft 134 through gears 129 and 128 and slip clutch 130. Since pinion gear 133 remains fixed by the restraint from frictional brake 119, pinion gear 137 rotates CW as denoted by the arrow, driving gear 138. Hence, shaft 143 which is fixedly attached to the latter gear drives the needle of the time-to-intercept indicator 18 CCW or towards zero. When gear 141 is stopped by stop 142, continued rotary drive from motor 16 is accommodated by slippage at overload clutch 153. Thus, concurrent with the linear rotation of the cases of potentiometers R13 and R14, the time-to-intercept indicator 18 is approaching zero during the running mode of operation.

Consider next the advance mode of operation which may be best described in connection with the illustrative embodiment shown in FIG. 6. With respect to this figure as viewed from the left, the full-arrow convention therein used represents direction of motion relative to this mode of operation. Conversely, the half-arrow notation re-

lates to direction of motion with respect to the retract mode of operation, whose description follows. In the advance mode of operation, the timing mechanism effects the concurrent expansion of the interceptor circle with the projection of a fictitious target, cursor dot S, on the screen of the PPI scope until a unique intersection occurs. During this operation, manual crank 19 is pushed forward engaging the conic surface 97 with collar 98. The motor 16 is running, advancing the time drive system and the time to intercept indicator 18 to zero, as previously discussed in connection with FIG. 7. In this respect, the rotary motion associated with the time drive system is not designated in the view of FIG. 6, but should be understood as being present. Clockwise knob motion causes gear 99 to effect displacement of the wipers of both potentiometers in a direction away from the respective stops 110 and 127. With respect to potentiometer R13, the rotary motion therefor is transmitted to gears 99, 101, 115 and 113. In the case of potentiometer R14, this coupling is provided through gears 99, 101, 116, 17, 118, 121, 122 and 123. The knob motion also drives the time-to-intercept system including the needle of indicator 18 towards zero through two paths. A direct drive is provided through the unidirectional clutch 91, gears 92, 147, 146 and 144, the rotary motion involved causing pinion gear 137 to rotate in the direction indicated thereon by a full arrow. An alternate drive stems from the rotation of gear 121 which drives pinion gear 133 in a direction as also indicated by a full arrow. Since the former motion is more rapid at the differential than the latter, spider shaft 134 slips CW with respect to slip clutch 130, as indicated by the dashed full arrow. Thus, the assembly consisting of gear 136 and shaft 140 rotates in a "plane" perpendicular to spider shaft 134. When the time-to-intercept system reaches stop 142, slip clutch 145 begins to slip and the continued rotation of knob 19 will result in gear 144 slipping CCW with respect to shaft 143. Continued manual cranking now effects a reversal or CCW rotation of the spider shaft, indicated by the dotted full arrow notation, as the potentiometer wipers continue to advance. The assembly including gear 136 and shaft 140 will now revolve CCW in a "plane" perpendicular to the spider shaft, as indicated by the dotted full arrow. In the advance mode of operation, rotation of gear 102 imparts motion to a gear train comprising 103, 94, 104 and 105, turning one face of clutch 106. Since the latter member is not energized, the rotary motion denoted above is not pertinent at this time. Thus, the advance mode of operation effects the projection of the wipers of both time potentiometers into future time relative to the chronometric rate of rotation of the potentiometer cases, concurrent with the advance of the time-to-intercept indicator 18 to zero.

The retract mode of operation next to be discussed immediately follows the advance mode of operation and is concerned with the return of the wipers of both the cursor and interceptor or time potentiometers to current time position, and in particular, with the setting of the time-to-intercept indicator 18. The rotary motions involved in the retract mode of operation are indicated in FIG. 6 by means of the half-arrow notation, previously mentioned. As in the advance mode of operation, motor 16 is running continuing to drive the potentiometer cases in a CCW direction and the time-to-intercept system. Also, during retract operation, knob 19 is maintained forward as before. However, its rotation is now in a CCW direction. This motion effects return of the wiper of the cursor time potentiometer against stop 127 while the wiper of the interceptor time potentiometer approaches stop 110. The drive path for both wiper shafts is the same as in the advance mode of operation. Since stop 110 is a movable stop fixed on the casing, it will not be reached except by overriding slip clutch 155. Under certain conditions, this overriding action may be advisable and can be achieved by applying additional torque to handwheel 19 after stop 127 has been reached. The wiper of cursor

time potentiometer R14 is never returned to zero, but rather, is displaced according to the elapsed time, thereby developing a voltage which is representative of the target's current position along the cursor. Consequently, the cursor dot S will be returned into superposition with the target video indicated by point T' in FIG. 1. With regards to the setting of the time-to-intercept indicator 18, the required drive for performing this task is obtained differentially from motor 16 and the manual rotation of knob 19. Since the drive from the motor advances gear 144 CCW or towards zero, its chronometric rate of speed is relatively slow compared to the CW rotation imparted by gear 144 by manual cranking. The latter is thereby the dominant drive transmitted through the differential 17. The drive from the motor is herein the motion present during the running mode of operation and is coupled through gears 152, 151, 149, 129, 128, slip clutch 130 to shaft 134. The rotary motion from crank 19 is transmitted through gears 99, 101, 116, 117, 118, 121, 131, 133, 136, 137 to 138. Thus, indicator dial 18 is automatically set to the time required for a target interception when stop 127 is reached. It should be noted that gear 144 and shaft 143 supply CCW rotation of gear 92, as indicated by the half-arrow notation. The rate of CCW rotation of this gear is less than the rate of CCW rotation of the knob shaft 93, so that the gear is turning CW with respect to the shaft and one-way-clutch 91 overrides. The continual rotation of the knob shaft 93 during the retract mode of operation will first cause stop 127 to be reached and slip clutch 155 to override, and then when stop 110 is reached, slip clutch 114 overrides. Thus, the essential function performed in the retract mode of operation involves the return of the wipers of both potentiometers to current time position, and coterminous therewith, the time required to make the interception is automatically set on the time-to-intercept indicator.

The reset mode of operation is primarily concerned with the return of the potentiometer cases including wipers to their initial positions, and the zeroing of the time-to-intercept indicator. The more pertinent structural elements involved in the reset mode of operation are illustrated in the view of FIG. 8. In this mode, the knob shaft 93 is pulled out, engaging the conic surface 96 with its companion collar 95, as indicated in the partially broken away view. Switch S301 is closed to its alternate position, disrupting motor excitation and effecting energization of control clutch 106, both sections of which are now engaged for common rotation. The clockwise rotation of knob 19 during reset is imparted to gears 94, 104, 105, 107 through clutch 106 and gears 108, 109 and 111. Thus, both potentiometer cases turn in a CW direction, as indicated, toward their initial position, the action terminating when the common stop 112 is reached. Concurrent with the return of the potentiometer cases, the rotation of knob shaft 93 also drives the wipers of both the cursor and interceptor time potentiometers to their associated stops 127 and 110, respectively, thereby effecting zeroing of the wipers. With respect to the cursor time potentiometer R14, this rotation is transmitted through a gear train comprising gears 103, 102, 116, 117, 118, 121, 122 and 123. In a comparable manner, the drive for the wiper of the interceptor time potentiometer R13 is transmitted through a gear train comprising 103, 102, 115 and 113. Differential displacement between the wipers of the potentiometers is accommodated by slippage at slip clutch 114, thus insuring for positive zeroing. The clockwise rotation of knob 19 also effects zeroing of indicator 18 through unidirectional clutch 91 and gears 92, 147, 146 and 144. The gear train for expressly performing this function is not shown in its entirety in the view of FIG. 8, but may be readily seen in the illustration of FIG. 6. Slip clutch 145 therein also illustrated in the latter view will slip when stop 142 is reached, and is also true of slip clutch 130, which accommodates slippage at the spider shaft 134. Thus, in the manner described above,

the reset mode of operation effects the rezeroing of both potentiometers including the time-to-intercept indicator.

Insofar as the technique for operating the inventive apparatus is concerned, there are two general steps in the use of the computer. First, it is assumed that if the instant invention is employed in a typical airborne application wherein the inventive apparatus is incorporated as a part of an airborne early warning radar installation, the indicator display is both ground and azimuth stabilized as hereinbefore mentioned, and therefore, any motion of the target on the scope is its motion relative to earth. Having observed a target, the operator places the origin of the cursor line over the target to be investigated, point T of FIG. 1, and at the same instant, the timing motor is started. This causes the time potentiometer R14 to advance from zero and an output voltage from it to be impressed across the target speed potentiometer R80. The resultant output from the speed potentiometer is applied to the range strobe and causes a cursor dot S to be originated at the origin of the cursor line and advance outward at a rate dependent upon the product of the time and target speed. The direction of motion of the dot is matched to that of the target by rotating the cursor line by the cursor bearing control 33. The rate of movement of the dot is matched to that of the target by varying the target speed knob 74. When synchronization is achieved, step 1 is complete, the target speed and course having been ascertained. This operation takes less than a minute.

Step 2 of the solution to the intercept problem requires the control officer using the computer to have further knowledge of the location and altitude of the interceptor aircraft. Other information concerning the range and speed capabilities of the interceptor are assumed known as hereinbefore mentioned. These facts, and also various tactical considerations, will indicate an optimum interceptor speed which is then set on an interceptor speed potentiometer R90, calibrated in knots. The circle center is then placed over the interceptor position, point I of FIG. 1, by using joystick 62. This is readily accomplished if the circle is diminished in size by retracting the timing mechanism until stop 110 is reached. This action will not cause the target dot to be displaced from the current position of the target, point T', portrayed in FIGURE 1. The time dial or indicator 18 is now advanced with the time modifier knob 19, as in the advance mode of operation, causing the circle to expand in size about the interceptor position and the cursor dot S to move out from the current target position. At a unique point in space, visibly identified on the cathode ray tube, the circle will intersect the cursor sweep line at the cursor dot, point P of FIG. 1. The point of intercept is thus established since this is a graphical representation of how far each aircraft will fly at its predetermined speed in the identical length of time. The course of the target is, of course, fixed as far as the control officer is concerned; however, the interceptor can fly to any point on the circle as presented on the screen of the PPI scope, since its heading can be established by the control officer. To facilitate the determination of the required interceptor heading on dial 82, an azimuth circle dot D, controlled by the interceptor azimuth circle resolver control 67, is displayed on the periphery of the circle. When control 67 is rotated so that the dot is superimposed over point P, dial 82 is automatically set to the correct intercept heading, measured from a stabilized north reference. Hence, an operator employing the operational steps herein set forth is able to determine an intercept course and the flight time to the interception point.

Solution to the so-called offset intercept approach can also be effected utilizing the following special technique. In this instance, the intercept is made from a fictitious point in space so located relative to the target that a final approach to the target can be made from a predetermined angle and distance. This fictitious point may be determined on the face of the PPI scope by relocating point T

an offset distance from the actual target video with the aid of cursor joystick 64, and thereupon, a determination of the fictitious point is made in accordance with step 2 above. The offset distance may alternatively be effected by auxiliary potentiometer means not illustrated in the drawings of the instant invention and interposed in the signal control leads of the cursor joystick circuit 65 for selective insertion or removal of supplemental D.C. potentials representing N-S and E-W components of offset distance. Hence, in this manner, the inventive intercept computer not only is capable of obtaining data involving a direct course approach to a target, but also, provides solution of problems in which the intercept is to be made from a fictitious point in space so located relative to the target that final approach to the target can be made from a predetermined angle and distance.

Thus, in the manner set forth, the instant invention provides for an intercept computer which when incorporated as a part of an early warning radar set provides for readily determining the proper heading and time required to intercept a remote target. The information thus obtained during the course of an intercept problem is relayed by conventional data link transmission means to the interceptor aircraft which then may proceed with dispatch to intercept a target. In addition, solutions to other problems of interest to a control officer may be obtained, making it possible to determine the time and speed factors involved in vectoring an aircraft to any point displayed on a radar PPI indicator. The speed of any moving target may also be quickly determined, and predictions regarding the future locations of targets can be made at any time. Thus, through use of the computer, it is possible to determine the ability of an interceptor to make an intercept, given certain conditions of speed differential, interceptor and target locations.

The following tabulation lists illustrative values of the electrical elements used in the preferred embodiment of the instant invention:

It should be understood, of course, that the foregoing disclosure relates to only a preferred embodiment of the invention and that numerous modifications or alterations may be made therein without departing from the spirit and the scope of the invention as set forth in the appended claims.

What is claimed is:

1. An intercept computer for determining a course of approach to a target, comprising a timing mechanism for extrapolating present position into future position by providing a parameter representative of a time interval extending from a present time to a predetermined future time, a first multiplication means for producing an interceptor distance product equal to a predetermined interceptor speed multiplied by said parameter, a second multiplication means for obtaining a target distance product equal to target speed multiplied by said parameter, and means for projecting the target distance product along a path coincident with the direction of travel of said target, whereby an intersection of the extrapolated position of the target with the extrapolated position of the interceptor represents the point of interception of said target.

2. An intercept computer for determining a course of approach to a target, comprising a timing mechanism including manual time modifying means for extrapolating present position into future position by providing a parameter representative of a time interval extending from a present time to a predetermined future time, a first multiplication means for producing an interceptor distance product equal to a predetermined interceptor speed and

said parameter, a second multiplication means for obtaining a target distance product equal to target speed multiplied by said parameter, means for projecting the target distance product along a path coincident with the direction of travel of said target, and a time dial operably coupled with said timing mechanism to indicate expected time of intercept upon retracting of the manual position modifying means from future time to current position, whereby an intersection of the extrapolated position of the target with the extrapolated position of the interceptor represents the point of interception of said target.

3. An intercept computer for determining a collision course approach between an interceptor and a target, comprising a first multiplication means including a first time potentiometer for producing an interceptor distance product, a second multiplication means including a second time potentiometer for producing a target distance product, means for projecting the target distance product along a path coincident with the direction of travel of said target, 15 a timing mechanism coupled to said first and second time potentiometers to develop respective electrical outputs proportional to time, and manual means operable to modify the respective electrical outputs of said potentiometers for concurrently extrapolating present target and interceptor positions to future positions, respectively, whereby an intersection of the extrapolated position of the target with the extrapolated position of the interceptor represents the point of interception of said target.

4. An intercept computer for determining a collision course approach between an interceptor and a target comprising, a timing mechanism for extrapolating present position into future position by providing a parameter representative of a time interval extending from a present time to a predetermined future time, a first multiplication 30 means for producing an interceptor distance product equal to a predetermined interceptor speed multiplied by said parameter, a second multiplication means to effect a target distance product equal to target speed multiplied by said parameter, for projecting the target distance product along a path coincident with the direction of travel of said target, and means for obtaining a target intercept heading, whereby an intersection of the extrapolated position of the target with the extrapolated position of the interceptor represents the point of interception with said target.

5. An intercept computer for determining a collision course approach between an interceptor and a target, a timing mechanism including manual time modifying means for extrapolating present position into future position by providing a parameter representative of a time interval extending from a present time to a predetermined future time, a first multiplication 45 means for producing an interceptor distance product equal to a predetermined interceptor speed and said parameter, a second multiplication means to effect a target distance product equal to target speed multiplied by said parameter, means for projecting the target distance product along a path coincident with the direction of travel of said target, means for obtaining a target intercept heading, and a time dial operably coupled with said timing mechanism to indicate expected time of intercept upon retracting of the manual time modifying means from the future position to the current position, whereby an intersection of the extrapolated position of the target with the extrapolated position of the interceptor represents the point of interception with said target.

6. An intercept computer for determining a collision course approach between an interceptor and a target, comprising a first multiplication means including a first time potentiometer for producing an interceptor distance product, a second multiplication means including a second time potentiometer for producing a target distance product, means for projecting the target distance product along a path coincident with the direction of travel of said target, means for obtaining a target intercept heading, a timing 70 mechanism including a constant speed motor coupled to

said first and second time potentiometers to develop respective electrical outputs proportional to time, and manual means operable to modify the respective electrical outputs of said potentiometers for concurrently extrapolating present target and interceptor positions to future positions, respectively, whereby an intersection of the extrapolated position of the target with the extrapolated position of the interceptor represents the point of interception with said target.

7. In an early warning radar system having a plan position indicator including a rotating radial sweep presentation, an intercept computer for computing a target intercept point by extrapolating present position of a target and an interceptor to respective future positions thereof comprising, video channel means for supplying target and interceptor video to said indicator, means for generating a slewable circular pattern of radius proportional to the product of a predetermined interceptor speed and a determinable future time interval, means for producing a slewable cursor sweep rotatively controllable about the origin thereof to coincide with target direction, means for producing a cursor strobe potential having a selectively controllable delay for obtaining synchronism of a cursor dot with the speed of the target video, a timing mechanism including time modifying means operable to vary the time parameter for projecting the cursor dot along the cursor sweep concurrently with proportionate increase in the radius of said circular pattern, and means for effecting a time shared presentation of said radial sweep, cursor sweep, and circular pattern together with coherent insertion of video including the cursor strobe potential at the video channel means to effect a coordinated display on said indicator, the circular pattern intersecting the cursor sweep with the cursor dot being uniquely superposed at the intersection at a determinable future time to establish the target intercept point.

8. In an early warning radar system having a plan position indicator including a rotating radial sweep presentation, an intercept computer for computing a target intercept point by extrapolating present position of a target and an interceptor to respective future positions thereof comprising, video channel means for supplying target and interceptor video to said indicator, means for generating a slewable circular pattern of radius proportional to the product of a predetermined interceptor speed and a determinable future time interval, means for producing a slewable cursor sweep rotatively controllable about the origin thereof to coincide with target direction, means for producing a cursor strobe potential having a selectively controllable delay for obtaining synchronism of a cursor dot with the speed of target video, a timing mechanism including time modifying means operable to vary the time parameter for projecting to effect projection of the cursor dot along the cursor sweep concurrently with proportionate increase in the radius of said circular pattern, means for generating a circle strobe potential having a selectively controllable delay for displaying a circle azimuth dot movable about the periphery of the circular pattern to provide target intercept heading, and means for effecting a time shared presentation of said radial sweep, cursor sweep, and circular pattern together with coherent insertion of video including cursor and circle strobe potentials at the video channel means to effect a coordinated display on said indicator, the circular pattern intersecting the cursor sweep with both the cursor dot and circle azimuth dot being uniquely superposed at the intersection at a determinable future time to establish the target intercept point.

9. In an early warning radar system having a plan position indicator including a rotating radial sweep presentation, an intercept computer for computing a target intercept point by extrapolating present target and interceptor positions to respective future positions thereof comprising, video channel means for supplying target and interceptor video to said indicator, means including a first time

5 potentiometer for generating a slewable circular pattern of radius proportional to the product of a predetermined interceptor speed and a determinable future time interval, means for producing a slewable cursor sweep rotatively controllable about the origin thereof to coincide with target direction, means including a second time potentiometer for producing a cursor strobe potential having a selectively controllable delay for obtaining synchronism of a cursor dot with the speed of the target video, a timing mechanism operably coupled with said first and second time potentiometers to develop respective electrical outputs proportional to time, manual means operable to modify the electrical outputs of said first and second time potentiometers for advancing said cursor dot along the cursor sweep concurrently with a proportionate increase in the radius of said circular pattern, and means for effecting a time shared presentation of said radial sweep, cursor sweep, and circular pattern with coherent insertion of video including the cursor strobe potential at the video 10 channel means to effect a coordinated display on said indicator, the circular pattern intersecting the cursor sweep with the cursor dot being uniquely superposed at the intersection at a determinable future time to establish the target intercept point.

15 20 25 30 35 40 45 50 55 60 10. In an early warning radar system having a plan position indicator including a rotating radial sweep presentation, an intercept computer for computing a target intercept point by extrapolating present target and interceptor positions to respective future positions thereof comprising, video channel means for supplying target and interceptor video to said indicator, means including a first time potentiometer for generating a slewable circular pattern of radius proportional to the product of a predetermined interceptor speed and a determinable future time interval, means for producing a slewable cursor sweep rotatively controllable about the origin thereof to coincide with target direction, means including a second time potentiometer for producing a cursor strobe potential having a selectively controllable delay for obtaining synchronism of a cursor dot with the speed of the target video, a timing mechanism operably coupled with said first and second time potentiometers to develop respective electrical outputs proportional to time, manual means operable to modify the electrical outputs of said first and second time potentiometers for advancing said cursor dot along the cursor sweep concurrently with a proportionate increase in the radius of the circular pattern, means for generating a circle strobe potential having a selectively controllable delay to effect display of a circle azimuth dot movable about the periphery of the circular pattern to provide target intercept heading, and means for producing a time shared presentation of said radial sweep, cursor sweep, and circular pattern together with coherent insertion of video including cursor and circle strobe potentials at the video channel means, thereby providing a coordinated display on said indicator, the circular pattern intersecting the cursor sweep with both the cursor dot and circle azimuth dot being uniquely superposed at the intersection at a determinable future time to establish the target intercept point.

11. In an early warning radar system having a plan position indicator including a rotating radial sweep presentation, an intercept computer for computing a target intercept point by extrapolating present target and interceptor positions to respective future positions thereof comprising, video channel means for supplying target and interceptor video to said indicator, means including a first time potentiometer for generating a slewable circular pattern of radius proportional to the product of a predetermined interceptor speed and a determinable future time interval, means for producing a slewable cursor sweep rotatively controllable about the origin thereof to coincide with target direction, means including a second time potentiometer for producing a cursor strobe potential having a selectively controllable delay for obtaining synchronism of a

cursor dot with the speed of the target video, a timing mechanism including a time dial operably coupled with said first and second time potentiometers to develop respective electrical outputs proportional to time, manual means reversibly operable to modify the electrical outputs of said first and second time potentiometers for selectively advancing and retracting said cursor dot along the cursor sweep concurrently with proportionate variation in the radius of said circular pattern, and means for producing a time shared presentation of said radial sweep, cursor sweep, and circular pattern with coherent insertion of video including the cursor strobe potential at the video channel means, thereby providing for a coordinated display on said indicator, the circular pattern intersecting the cursor sweep with the cursor dot being uniquely superposed at the intersection at a determinable future time to establish the target intercept point, the time dial being set to expected time of intercept upon retracting the manual means, whereby the cursor dot is returned in coincident position with the present position of the target video on the indicator.

12. In an early warning radar system having a plan position indicator including a rotating radial sweep presentation, an intercept computer for computing a target intercept point by extrapolating present target and interceptor positions to respective future positions thereof comprising, video channel means for supplying target and interceptor video to said indicator, means including a first time potentiometer for generating a slewable circular pattern of radius proportional to the product of a predetermined interceptor speed and a determinable future time interval, means for producing a slewable cursor rotatively controllable about the origin thereof to coincide with target direction, means including a second time potentiometer for producing a cursor strobe potential having a selectively controllable delay for obtaining synchronism of a cursor dot with the speed of the target video, a timing mechanism including a time dial operably coupled with said first and second time potentiometers to develop respective electrical outputs proportional to time, manual means reversibly operable to modify the electrical outputs of said first and second time potentiometers for selectively advancing and retracting said cursor dot along the cursor sweep concurrently with proportionate variation in the radius of said circular pattern, means for generating a circle strobe potential having a selectively controllable delay to effect display of a circle azimuth dot movable about the periphery of the circular pattern to provide target intercept heading, and means for producing a time shared presentation of said radial sweep, cursor sweep, and circular pattern together with coherent insertion of video including cursor and circle strobe potentials at the video channel means thereby providing for a coordinated display on said indicator, the circular pattern intersecting the cursor sweep with the cursor dot and circle azimuth dot being uniquely superposed at the intersection at a determinable future time to establish the target intercept point, the time dial being set to expected time of intercept upon retracting the manual means from the extrapolated target and interceptor positions, whereby the cursor dot is returned in coincident position with the present position of the target video on the indicator.

13. In an early warning radar system having a plan position indicator including a rotating radial sweep presentation, an intercept computer for computing a target intercept point by extrapolating present target and interceptor positions to respective future positions comprising, video channel means for supplying target and interceptor video to said indicator, means including a first time potentiometer for generating a slewable circular pattern of radius proportional to the product of a predetermined interceptor speed and a determinable future time interval, means for producing a slewable cursor sweep rotatively controllable about the origin thereof to coincide with target direction, means including a second time

potentiometer for producing a cursor strobe potential having a selectively controllable delay to provide display of a cursor dot in synchronism with the speed of the target video, a timing mechanism operably coupled with said first and second time potentiometers to develop respective electrical outputs proportional to time, manual means operable to modify the electrical outputs of said first and second time potentiometers for advancing said cursor dot along the cursor sweep concurrently with proportionate increase in the radius of said circular pattern, means for generating a circle strobe potential having a selectively controllable delay for display of a circle azimuth dot movable about the periphery of the circular pattern to provide target intercept heading, the video channel means including a video switch means and a strobe switch means selectively responsive to bistable excitation to provide coherent insertion of video, the cursor potential, and the circle strobe potential, during presentation of the radial sweep, cursor sweep, and the circular pattern, respectively, and means for selectively producing in a predetermined ratio a time shared presentation of said radial sweep, cursor sweep, and circular pattern to effect a coordinated display on said indicator, the circular pattern intersecting the cursor sweep with the cursor dot and circle azimuth dot being uniquely superposed at the intersection at a determinable future time to establish the target intercept point.

14. In an early warning radar system having a plan position indicator including a rotating radial sweep presentation, an intercept computer for computing a target intercept point by extrapolating present target and interceptor positions to respective future positions thereof comprising, video channel means for supplying target and interceptor video to said indicator, means including a first time potentiometer for generating a slewable circular pattern of radius proportional to the product of a predetermined interceptor speed and a determinable future time interval, said last named means including oscillator means having a sinusoidal output voltage which is impressed across said first potentiometer, said output voltage having a frequency greater than the pulse repetition frequency of the radar system, means for producing a slewable cursor rotatively controllable about the origin thereof to coincide with target direction, means including a second time potentiometer for producing a cursor strobe potential having a selectively controllable delay for obtaining synchronism of a cursor dot with the speed of the target video, a timing mechanism operably coupled with said first and second time potentiometers to develop respective electrical outputs proportional to time, manual means operable to modify the electrical outputs for advancing the cursor dot along the cursor sweep concurrently with proportionate increase in the radius of said circular pattern, and means for producing a time shared presentation of said radial sweep, cursor sweep, and circular pattern together with coherent insertion of video including the cursor strobe potential at the video channel means to provide a coordinated display on said indicator, the circular pattern intersecting the cursor sweep with the cursor dot being uniquely superposed at the intersection at a determinable future time to establish the target intercept point.

15. In an early warning radar system having a plan position indicator including a rotating radial sweep presentation, an intercept computer for computing a target intercept point comprising, video channel means for supplying target and interceptor video to said indicator, means including a first time potentiometer for generating a slewable circular pattern of radius proportional to the product of a predetermined interceptor speed and a determinable future time interval, said last named means including oscillator means having a sinusoidal output voltage which is impressed across said first potentiometer, said output voltage having a frequency greater than the pulse repetition frequency of the radar system, means for

producing a slewable cursor sweep rotatively controllable about the origin thereof to coincide with target direction, means including a second time potentiometer for producing a cursor strobe potential having a selectively controllable delay for obtaining synchronism of a cursor dot with the speed of the target video, a timing mechanism operably coupled with said first and second time potentiometers to develop respective electrical outputs proportional to time, manual means operable to modify the electrical outputs of said first and second time potentiometers for advancing said cursor dot along the cursor sweep concurrently with proportionate increase in the radius of said circular pattern, means operably connected electrically to said oscillator means for generating the circle strobe potential having a selectively controllable delay to effect display of a circle azimuth dot movable about the periphery of the circular pattern to provide target intercept heading, and means for producing a time shared presentation of said radial sweep, cursor sweep, and circular pattern together with coherent insertion of video including cursor and circle strobe potentials at the video channel means thereby providing for a coordinated display on said indicator, the circular pattern intersecting the cursor sweep with the cursor dot and circle azimuth dot being uniquely superposed at the intersection at a determinable future time to establish the target intercept point.

16. In an early warning radar system having a plan position indicator including deflection means for producing a rotating radial sweep presentation, an intercept computer for computing a target intercept point comprising, video channel means for supplying target and interceptor video to said indicator, oscillator means having a sinusoidal output of frequency greater than the pulse repetition frequency of the radar system, a first time potentiometer electrically connected for energization to said oscillator means, multiplication means including a potentiometer adjusted according to a known interceptor speed to effect an A.C. output voltage representing an interceptor distance product equal to the interceptor speed multiplied by a given future time interval, a phase shift network operable on the latter voltage to produce a pair of A.C. voltages having phases which are in quadrature relation to effect generation of a circular pattern of radius proportional to said interceptor distance product, amplifier means to amplify each of the A.C. voltage phases, circle positioning means including a movable element to develop a plurality of D.C. levels of polarity and magnitude corresponding to the displacement of the movable element from its neutral position, a component mixer means to produce a composite slewable circle signal by combining each of the D.C. levels with the respective A.C. voltage phases, switch means responsive to bistable excitation for selectively supplying the slewable circle signal to the deflection means of the radar system for presentation of a slewable circular pattern, means for producing a slewable cursor sweep rotatively controllable about the origin thereof to coincide with target direction, means including a second time potentiometer for producing a cursor strobe potential having a selectively controllable delay to effect synchronism of a cursor dot with the speed of the target video, a timing mechanism operably coupled with said first and second time potentiometers to develop respective electrical outputs proportional to time, manual means operable to modify the electrical outputs of said first and second time potentiometers for advancing said cursor dot along the cursor sweep concurrently with proportionate increase in the radius of said circular pattern, means operably connected electrically with the oscillator means for generating a circle strobe potential, having a selectively controllable delay to effect display of a circle azimuth dot movable about the periphery of the circular pattern to provide target intercept heading, and means for effecting a time shared presentation of said radial sweep, cursor sweep, and circular pattern with coherent insertion of

video including cursor and circle strobe potentials at the video channel means to effect a coordinated display on said indicator, the circular pattern intersecting the cursor sweep with the cursor dot and circle azimuth dot being uniquely superposed at the intersection at a determinable future time to establish the target intercept point.

17. In an early warning radar system having a plan position indicator including a rotating radial sweep presentation, an intercept computer for computing a target intercept point comprising, video channel means for supplying target and interceptor video to said indicator, means including a first time potentiometer for generating a slewable circular pattern of radius proportional to the product of a predetermined interceptor speed and a determinable future time interval, means for producing a slewable cursor sweep rotatively controllable about the origin thereof to coincide with target direction, a second time potentiometer, a timing mechanism operably coupled with said first and second time potentiometers to develop respective electrical outputs proportional to time, means operably connected electrically with said second time potentiometer including a cursor speed potentiometer which is maintained substantially adjusted to changes in target speed to produce a proportionate D.C. output level, a D.C. amplifier for amplifying the D.C. output level, switch means responsive to bistable excitation to render the amplified D.C. level available at the output of the switch means during cursor sweep presentation, a phantastron stage including a cathode follower responsive to the switch means to convert the amplified D.C. level into a pulse output having a duration proportional to the amplitude of the applied D.C. level, a trigger amplifier including a differentiating circuit in the input thereof to produce a trigger output selectively delayed according to the duration of the pulse output, a blocking oscillator responsive to said trigger output to produce a cursor strobe potential which is applied during cursor sweep presentation to said video channel means for insertion thereof as a cursor dot, which cursor dot is thus characterized by a selectively controllable delay for obtaining synchronism with the target video to obtain target speed, manual means operable to modify the electrical outputs of said time potentiometers for advancing said cursor dot along the cursor sweep concurrently with proportionate increase in the radius of said circular pattern, means for generating a circle strobe potential having a selectively controllable delay for display of a circle azimuth dot movable about the periphery of the circular pattern to provide target intercept heading, and means for producing a time shared presentation of said radial sweep, cursor sweep, and circular pattern with coherent insertion of video including cursor and circle strobe potentials at the video channel means to effect a coordinated display on said indicator, the circular pattern intersecting the cursor sweep with both the cursor dot and the circle azimuth dot being uniquely superposed at the intersection at a determinable future time to establish the target intercept point.

18. In an early warning radar system having a plan position indicator including a rotating radial sweep presentation, an intercept computer for computing a target intercept point comprising, video channel means for supplying target and interceptor video to said indicator, oscillator means having a sinusoidal output voltage of frequency greater than the pulse repetition frequency of the radar system, means including a first time potentiometer operably connected electrically with said oscillator means for generating a slewable circular pattern of radius proportional to the product of a predetermined interceptor speed and a determinable future time interval, means for producing a slewable cursor rotatively controllable about the origin thereof to coincide with target direction, means including a second time potentiometer for producing a cursor strobe potential having a selectively controllable delay to effect display of a cursor dot in synchronism

with the speed of the target video, a timing mechanism operably coupled with said first and second time potentiometers to develop respective electrical outputs proportional to time, manual means operable to modify the electrical outputs of said first and second time potentiometers for projection of said cursor dot along the cursor sweep concurrently with proportionate increase in the radius of said circular pattern, resolver driver means responsive to said oscillator means to produce in the output thereof a sinusoidal signal having a relatively low driving impedance, resolver means including a rotatively controllable rotor winding operably connected electrically to said resolver driver means to resolve the sinusoidal signal into voltage components each of a phase and amplitude corresponding to the angular displacement of the rotor winding, indication means mechanically linked with the rotor winding to provide target intercept heading measured from a given reference, a phase shift mixer responsive to the resolver means to recombine the voltage components into an A.C. signal having its phase retarded an amount proportional to the angular displacement of the rotor winding, an azimuth dot generating means responsive to said phase shift mixer to convert the A.C. signal into a strobe potential, switch means responsive to bistable excitation for selectively supplying the strobe potential to the video channel means for insertion thereof for display of a circle azimuth dot movable about the periphery of the circular pattern directly with rotary displacement of the rotor winding, and means for effecting a time shared presentation of said radial sweep, cursor sweep, and circular pattern with coherent insertion of video including cursor and circle strobe potentials at the video channel means to effect a coordinated display on said indicator, the circular pattern intersecting the cursor sweep with the cursor dot being uniquely superposed at the intersection at a determinable future time to establish the target intercept point, movement of the circle azimuth dot to coincidence with the cursor dot rendering the indication means set to the target intercept bearing.

19. In an early warning radar system having a plan position indicator including a rotating radial sweep presentation, an intercept computer for computing a target intercept point comprising, video channel means for supplying target and interceptor video to said indicator, oscillator means having a sinusoidal output of frequency greater than the pulse repetition frequency of the radar system, means including a first potentiometer operably connected electrically with said oscillator means for generating a slewable circular pattern of radius proportional to the product of a predetermined interceptor speed and a determinable future time interval, means for producing a slewable cursor sweep rotatively controllable about the origin thereof to coincide with target direction, means including a second time potentiometer for producing a cursor strobe potential having a selectively controllable delay for obtaining synchronism of a cursor dot with the speed of the target video, a timing mechanism for producing a chronometric rate of rotation of said first and second time potentiometers to develop respective electrical outputs proportional to time, manual means operable to modify the electrical outputs of said first and second time potentiometers for projection of said cursor dot concurrently with proportionate increase in the radius of said circular pattern, resolver driver means responsive to said oscillator means to produce in the output thereof a sinusoidal signal having a relatively low driving impedance, resolver means including a rotatively controllable rotor winding operably connected electrically to said resolver driver means to resolve the sinusoidal signal into voltage components each of a phase and amplitude corresponding to the angular displacement of the rotor winding, indication means mechanically linked with the rotor winding to provide target intercept bearing measured from a given reference, a phase shift mixer responsive to the resolver means to recombine the voltage components into an A.C.

signal having its phase retarded an amount proportional to the angular displacement of the rotor winding, clipper means responsive to said phase shift mixer to remove the alternating excursions of said A.C. signal at predetermined levels to produce a substantially square wave voltage, a blocking oscillator including a differentiating network in the input thereof operable on the square wave voltage of said clipper means to produce a strobe potential, switch means responsive to bistable excitation for selectively supplying the strobe potential to the video channel means for insertion thereof for display of a circle azimuth dot movable about the periphery of the circular pattern directly with rotary displacement of the rotor winding, and means for effecting a time shared presentation of said radial sweep, cursor sweep, and circular pattern with coherent insertion of video including cursor and circle strobe potentials at the video channel means to effect a coordinated display on said indicator, the circular pattern intersecting the cursor sweep with the cursor dot being uniquely superposed at the intersection at a determinable future time to establish the target intercept point, movement of the circle azimuth dot to coincidence with the cursor dot rendering the indication means set to the target intercept bearing.

20. In an early warning radar system having a plan position indicator including a rotating radial sweep presentation, an intercept computer for computing a target intercept point comprising, video channel means for supplying target and interceptor video to said indicator, means including a first time potentiometer having a wiper portion and a resistive portion for generating a slewable circular pattern of radius proportional to the product of a predetermined interceptor speed and a determinable future time interval, means for producing a slewable cursor rotatively controllable about the origin thereof to coincide with target direction, a second time potentiometer having a wiper portion and a resistive portion, a timing mechanism operably coupled to drive the resistive portions of said first and second time potentiometers to develop respective electrical outputs proportional to time, means including a cathode follower operably connected electrically with the wiper of said second time potentiometer including a cursor speed potentiometer disposed as a portion of the cathode load impedance of said cathode follower, said cursor speed potentiometer having a wiper which is maintained substantially adjusted to changes in target speed to produce a proportionate D.C. output level, a D.C. amplifier for amplifying the D.C. output level, switch means responsive to bistable excitation to render the amplified D.C. level available at the output of the switch means during cursor sweep presentation, means responsive to the amplified D.C. level to produce a cursor strobe potential having a selectively controllable delay proportional to the amplitude of the latter D.C. level to effect synchronism of a cursor dot with the speed of the target video, manual means operable to modify the electrical outputs of said first and second time potentiometers for projection of said cursor dot along the cursor sweep concurrently with proportionate increase in radius of said circular pattern, means for generating the circle strobe potential having a selectively controllable delay to effect display of a circle azimuth dot movable above the periphery of the circular pattern in coincidence with a determinable intercept point to provide target intercept heading, and means for selectively effecting a time shared presentation in a predetermined ratio of said radial sweep, cursor sweep, and circular pattern together with coherent insertion of video including cursor and circle strobe potentials at the video channel means thereby providing for a coordinated display on said indicator, the cursor and circle azimuth dot being uniquely superposed at a determinable future time to establish the target intercept point.

21. In an early warning radar system having a plan position indicator including a rotating radial sweep presentation, an intercept computer for computing a target

intercept point comprising, video channel means for supplying target and interceptor video to said indicator, means including a first time potentiometer having a wiper portion and a resistive portion for generating a slewable circular pattern of radius proportional to the product of a predetermined interceptor speed and a determinable future time interval, means for producing a slewable cursor sweep rotatively controllable about the origin thereof to coincide with target direction, a second time potentiometer having a wiper portion and a resistive portion, a timing mechanism operably coupled to drive the resistive portions of said first and second time potentiometers to develop respective electrical outputs proportional to time, means including a cathode follower operably connected electrically with the wiper of said second time potentiometer including a cursor speed potentiometer disposed as a portion of the cathode load impedance of said cathode follower, said cursor speed potentiometer having a wiper which is maintained substantially adjusted to changes in target speed to produce a proportionate D.C. output level, a D.C. amplifier for amplifying the D.C. output level, switch means responsive to bistable excitation to render the amplified D.C. level available at the output of the switch means during cursor sweep presentation, means including a cathode follower responsive to the switch means to convert the amplified D.C. level into a pulse output having a duration proportional to the amplitude of the applied D.C. level, a trigger amplifier including a differentiating circuit in the input thereof to effect a trigger output selectively delayed according to the duration of the pulse output, a blocking oscillator responsive to said trigger output to produce a cursor strobe potential which is applied during cursor sweep presentation to said video channel means for insertion thereof as a cursor dot, which cursor dot is thus characterized by a selectively controllable delay to effect synchronism with the target video to obtain target speed, manual means operable to modify the position of the wiper portion relative to the resistive portion of both first and second potentiometers to obtain electrical outputs for advancing said cursor dot along the cursor sweep concurrently with proportionate increase in the radius of said circular pattern, means for generating a circle strobe potential having a selectively controllable delay for display of a circle azimuth dot movable about the periphery of the circular pattern in coincidence with a determinable intercept point to provide target intercept heading, and means for selectively producing in a predetermined ratio a time shared presentation of said radial sweep, cursor sweep, and circular pattern, the video channel means including a video switch means and a strobe switch means selectively responsive to bistable excitation to provide coherent insertion of video including cursor and circle strobe potentials at the video channel means to effect a coordinated display on said indicator, the circular pattern intersecting the cursor sweep with both the cursor dot and the circle azimuth dot being uniquely superposed at the intersection at a determinable future time interval to establish the target intercept point.

22. In an early warning radar system having a plan position indicator including deflection means for producing a rotating radial sweep presentation, an intercept computer for computing a target intercept point comprising, video channel means for supplying target and interceptor video to said indicator, means including a first time potentiometer for generating a composite slewable circle signal to provide for visual presentation of a slewable circular pattern of radius proportional to the product of a predetermined interceptor speed and a determinable future time interval, resolver means including a rotor winding operably connected electrically with the deflection means for sawtooth voltage energization, cursor switch means responsive to bistable excitation and operably connected electrically with the resolver means to selectively extract a radial sweep for presentation as a

cursor sweep, the rotor winding being manually operable to rotatively control the cursor sweep about its origin to coincide with target direction, means including a movable element for producing a slewing level signal of polarity and magnitude corresponding to the displacement of the movable element from its neutral position to effect control over the location of the cursor sweep on the face of the indicator, means including a second time potentiometer for producing a cursor strobe potential having a selectively controllable delay for obtaining synchronism of a cursor dot with the speed of the target video, a timing mechanism operably coupled with said first and second time potentiometers to develop respective electrical outputs proportional to time, manual means operable to modify the electrical outputs of said first and second time potentiometers for advancing said cursor dot concurrently with proportionate increase in radius of said circular pattern, a bistable device responsive to radar triggers to produce a bistable voltage at the pulse repetition frequency of the radar system, a frequency fractionating means responsive to the bistable device to subdivide in a predetermined ratio the frequency of the bistable voltage, a switch gate generator means responsive to the frequency fractionating means to produce an asymmetrical bistable gating voltage, driver means responsive to the switch gate generator to develop a substantially square wave driving voltage, means including a plurality of switch devices responsive to said driver means to reciprocally actuate said switch devices between two operable states for effecting the circular pattern or the cursor sweep presentation, the slewing level signal, the composite slewable circle signal, and the cursor strobe potential being supplied to said switch devices, a gate amplifier responsive to said bistable device to amplify and invert the bistable voltage thereof, a cursor driver cathode follower responsive in one state of the switch devices to the asymmetrical bistable gating voltage of the switch gate generator means or jointly in the alternate state of the switch devices to both the asymmetrical bistable gating voltage and the bistable voltage of the gate amplifier to produce a low impedance gating pulse, cathode follower means operably connected to the switch devices to selectively obtain the cursor slewing level signal or the composite slewable circle signal, and a gated clamp means responsive to the cathode follower means to effect synchronized clamping at the slewing level potential upon being gated by the bistable gating pulse of said cursor driver cathode follower, the cursor gated clamp means alternately supplying to the deflection means of the indicator the composite slewable circle signal to provide presentation of a circular pattern and the cursor slewing level signal to locate the electron beam of the indicator prior to the start of the cursor sweep trace, a time shared display of the cursor and circular pattern being integrated with the radial sweep with coherent insertion of video including the cursor strobe potential at the video channel means to effect a coordinated presentation on said indicator, the circular pattern intersecting the cursor sweep with the cursor dot being uniquely superposed at the intersection at a determinable future time to establish the target intercept point.

23. In an early warning radar system having a plan position indicator including deflection means for producing a rotating radial sweep presentation, an intercept computer for computing a target intercept point comprising, video channel means for supplying target and interceptor video to said indicator, means including a first time potentiometer for generating a composite slewable circle signal to effect visual presentation of a slewable circular pattern of radius proportional to the product of a predetermined interceptor speed and a determinable future time interval, resolver means including a rotor winding operably connected electrically with the deflection means for sawtooth voltage energization, cursor switch means responsive to bistable excitation and operably connected electrically with the resolver means to

selectively extract a radial sweep for presentation as a cursor sweep, the rotor winding being manually operable to rotatively control the cursor sweep about its origin to coincide with target direction, means including a movable element for producing a slewing level signal of polarity and magnitude corresponding to the displacement of the movable element from its neutral position to effect control over the location of the cursor sweep on the face of the indicator, means including a second time 10 potentiometer for producing a cursor strobe potential having a selectively controllable delay for obtaining synchronism of a cursor dot with the speed of the target video, a timing mechanism operably coupled with said first and second time potentiometers to develop respective 15 electrical outputs proportional to time, manual means operable to modify the electrical outputs of said first and second time potentiometers for advancing said cursor dot concurrently with proportionate increase in radius of said circular pattern, means for generating a circle strobe potential having a selectively controllable delay to effect 20 display of a circle azimuth dot movable about the periphery of the circular pattern in coincidence with a determinable intercept point to provide target intercept heading, a bistable device responsive to radar triggers to produce a bistable voltage at the pulse repetition frequency of the radar system, a frequency fractionating means responsive to the bistable device to subdivide in a predetermined ratio the frequency of the bistable voltage, a switch gate generator means responsive to the frequency fractionating means to produce an asymmetrical bistable 25 gating voltage, driver means responsive to the switch gate generator to develop a substantially square wave driving voltage, means including a plurality of switch devices responsive to said driver means to reciprocally actuate said switch devices between two operable states for effecting the circular pattern or the cursor sweep presentation, the slewing level signal, the composite slewable circle signal, the cursor strobe potential, and circle azimuth strobe potential being supplied to said switch devices, a gate amplifier responsive to said bistable device to 30 amplify and invert the bistable voltage thereof, a cursor driver cathode follower responsive in one state of the switch devices to the asymmetrical bistable gating voltage of the switch gate generator means or jointly in the alternate state of the switch devices to both the asymmetrical bistable gating voltage and the bistable voltage of the gate amplifier to produce a low impedance gating pulse, cathode follower means operably connected to the switch devices to selectively obtain the cursor slewing level signal or the composite slewable circle signal, and a gated clamp means responsive to the cathode follower means to effect synchronized clamping at the slewing level potential upon being gated by the bistable gating pulse of said cursor driver cathode follower, the cursor gated clamp means alternately supplying to the deflection means of the indicator the composite slewable circle signal to effect presentation of a circular pattern and the cursor slewing level signal to locate the electron beam of the indicator prior to the start of the cursor sweep trace, a time shared display of the cursor sweep and circular pattern being integrated with the radial sweep with the coherent insertion of video including cursor strobe and circle strobe potentials at the video channel means to provide a coordinated presentation on said indicator, the circular pattern intersecting the cursor sweep with the cursor dot and the circle azimuth dot being uniquely superposed at the intersection at a determinable future time to establish the target intercept point.

24. A timing mechanism comprising, potentiometer means to develop an electrical output proportional to the parameter of time, a motor having a substantially constant speed driving characteristic operably coupled with said potentiometer means, manual means reversibly operable to drive the potentiometer means to modify the electrical output according to said time parameter, differ-

ential means operably coupled with the motor and said manual means, and a time dial coupled to said differential means to receive the differential rotary output drive therefrom, the time dial being set to a finite time interval 5 upon retracting the manual means, whereby the future time is thereafter continually reduced toward zero at a chronometric rate.

25. A timing mechanism comprising, potentiometer means having a wiper portion and a resistive portion to develop an electrical output proportional to the parameter of time, a motor having a substantially constant speed driving characteristic coupled with said resistive portion, manual means reversibly operable to drive the wiper portion through a gear train to modify the electrical output 10 according to said time parameter, differential means operably coupled with the motor and said manual means, and a time dial coupled with the differential means to receive a differential rotary output drive therefrom, the time dial being set to a finite time interval upon retracting 15 the manual means, whereby the future time is thereafter continually reduced toward zero at a chronometric rate.

26. A timing mechanism comprising, potentiometer means having a wiper portion and a resistive portion to develop an electrical output proportional to the parameter of time, a motor having a substantially constant speed driving characteristic operably coupled with said resistive portion, manual means reversibly operable to drive the wiper portion to modify the electrical output according 20 to said time parameter, differential means operably coupled with the motor and said manual means, a time dial coupled to the differential means to receive a differential rotary output drive therefrom, and a unidirectional clutch operably interposed between the time dial and the manual means to effect relatively rapid initial zeroing of the time 25 dial upon advancing the manual means, the time dial being set to a finite time interval upon retracting the manual means, said finite time interval thereafter being continually reduced toward zero at a chronometric rate.

27. In an intercept computer, a timing mechanism comprising, a target time and an intercept time potentiometer means each having a wiper portion and a resistive portion to produce respective electrical outputs proportional to the parameter of time, a motor having a substantially constant speed characteristic operably coupled to the resistive 30 portions of said potentiometer means, manual means reversibly operable to concurrently drive the wipers of both potentiometer means to modify the electrical outputs according to said time parameter, differential means operably coupled with the motor and said manual means, a time dial coupled to said differential means to receive the differential rotary output drive therefrom, and slip clutch means operably interposed in rotary driving means of the wiper portion of the target time potentiometer, said latter potentiometer means including a fixed stop to provide a 35 limit position for the wiper thereof, said interceptor time potentiometer means including an operably associated stop fixedly mounted for common rotation with the resistive portion thereof and a companion cooperating member fixedly mounted for common rotation with the wiper thereof, the time dial being set to a finite time interval upon retracting the manual means to current time coincident with the arrival of the wiper portion of said first potentiometer means at its limit position, whereby further 40 retracting the manual means is accommodated by overriding the slip clutch means to render engagement of the movable stop with its companion cooperating member at which instance the target time potentiometer means has a proportionate electrical output corresponding to the elapsed running time and the interceptor time potentiometer has its electrical time output reduced to zero.

28. In an intercept computer, a timing mechanism comprising, a target time and an interceptor time potentiometer means each having a wiper portion and a resistive portion to produce respective electrical outputs proportional to the parameter of time, a motor having a sub-

stantially constant speed characteristic operably coupled with said resistive portions, manual means reversibly operable to concurrently drive the wiper portions of both potentiometers to modify the respective electrical outputs thereof, differential means operably coupled with the motor and said manual means, a time dial coupled to the differential means to receive a differential rotary output drive therefrom, and a unidirectional clutch operably interposed between the time dial and the manual means to effect relatively rapid initial zeroing of the time dial upon advancing the manual means, the time dial being set to a finite time interval upon retracting the manual means, said finite time interval thereafter being continually reduced toward zero at a chronometric rate.

29. The timing mechanism of claim 26 in which the mechanism embodies reset means, comprising a clutch operably interposed between the manual means and the resistive portion of both potentiometers, selective control means to activate the clutch and deactivate the motor,

and a reset rotary driving means responsive to the rotation of the manual means through said clutch in activated position to concurrently drive the wiper portion of both potentiometers, the manual means including a manually driven shaft normally disposed in a first axial position and axially movable to a second axial position to effect selective engagement with the reset means, whereby manual rotation of the shaft in its second axial position returns the wiper portion and resistive portion of each potentiometer toward zero.

UNITED STATES PATENT OFFICE
CERTIFICATE OF CORRECTION

Patent No. 3,088,108

April 30, 1963

Frederick E. Smith

It is hereby certified that error appears in the above numbered patent requiring correction and that the said Letters Patent should read as corrected below.

Column 29, line 63, for "V794" read -- C794 --; column 32, line 39, after "parameter," insert -- means --; column 40, line 22, for "azimuth" read -- azimuth --; line 24, for "warming" read -- warning --; line 61, for "above" read -- about --.

Signed and sealed this 17th day of December 1963.
